UNITED STATES PATENT OFFICE

2,335,368

CALCULATING MACHINE

Hans Uhlmann, Berlin-Steglitz, Germany, assignor to The National Cash Register Company, Dayton, Ohio, a corporation of Maryland

Application April 8, 1939, Serial No. 266,824
In Germany April 14, 1938

30 Claims. (Cl. 235—60)

This invention relates to mechanical multiplying machines and is particularly directed to a multiplying attachment or unit for use in connection with accounting or bookkeeping machines.

The present invention is directed to a compact and efficient multiplying mechanism adapted to be attached to the base of a well-known type of accounting machine, fully disclosed in United States Patents Nos. 1,197,276 and 1,197,278, issued September 5, 1916, to Halcolm Ellis; Nos. 2,038,717 and 2,082,098, issued respectively April 28, 1936, and June 1, 1937, to Raymond A. Christian; and No. 2,079,355, issued May 4, 1937, to Charles L. Lee. This multiplying mechanism does not in any way interfere with the normal operation of the accounting machine for business problems not requiring multiplication.

It is not the desire to confine the multiplying mechanism of this invention to use on the type of accounting machines referred to above, as it may, with minor alterations and adjustments, be adapted for use on most any type of accounting or business machine.

As presently constructed, the multiplying mechanism has a capacity of eight digits in the multiplicand and six digits in the multiplier, in either case two of the digits being decimals or tenths and hundredths of a dollar. The product capacity of the multiplying mechanism is 14 digits. However, as four of these product digits are decimals, it is considered necessary to print only two of the decimals (tenths and hundredths of dollars), making the total registering and printing capacity of the multiplying mechanism twelve digits.

Problem illustrating the capacity of the multiplying mechanism:

999,999.99 — Multiplicand (8 digits)
9,999.99 — Multiplier (6 digits)

899999991
899999991
899999991
899999991
899999991
899999991

9,999,989,900.00(01) — Product (14 digits,
only the 12 highest
orders being re-
corded)

A brief outline of the sequence of operations necessary to perform a problem of multiplication is as follows:

First, the multiplicand, which may have a maximum of eight digits, is set up on the keyboard of the accounting machine and the operation is initiated by depressing the multiplication key and the accounting machine starting bar. During this operation the multiplicand is printed and entered in the multiplying mechanism and may, if desired, be entered in one or more of the accumulators of the accounting machine. After the above multiplicand-entering operation, the machine comes to rest.

15 Next, the multiplier, which may have a maximum of six digits, is set up on the accounting machine keyboard and the machine released for another operation by depressing the multiplication key and the accounting machine starting bar.

20 During this operation the multiplier is entered in the multiplying mechanism and simultaneously printed, and may, if desired, also be entered in one or more of the accumulators of the accounting machine. At the end of the multiplier-entering cycle or operation, the accounting machine is disconnected from the multiplying mechanism and comes to rest.

25 Though the accounting machine comes to rest, the multiplying mechanism continues to operate and automatically performs six multiplying operations. During these six operations, the multiplicand is multiplied by the six digits of the multiplier and the partial products thus obtained are accumulated in a product accumulator having a capacity of fourteen denominational orders.

30 After the six multiplying operations, and while the multiplying mechanism is still operating, the accounting machine is operated in conjunction with the multiplying mechanism to automatically clear the product accumulator and transfer the product to the recording means of the accounting machine and, if desired, to one or more of the accumulators of the accounting machine.

35 With the foregoing brief outline in mind, it is broadly an object of this invention to provide a mechanical type of multiplying mechanism for use in connection with accounting and bookkeeping machines.

40 Another object of this invention is the provision of a mechanical multiplying mechanism which is compact in form, comparatively simple in construction, and efficient in operation, and one which is readily adaptable for use in connection with accounting machines of the type referred to above.

Another object is to supply a multiplying mechanism having a plurality of computing devices or multiplication tables for each digit of the multiplicand, in which the units and tens of the partial products are computed separately and combined with other partial products in a product accumulator to form a complete product.

Still another object is the provision of a multiplying mechanism which operates on the partial product principle and in which the units and tens values of the partial products are computed separately and successively combined to form a complete product.

A further object is to provide a multiplying mechanism having a plurality of computing devices or multiplication tables controlled jointly by the multiplicand and the multiplier, for effecting a quick method of multiplication.

A still further object is the provision of a multiplying mechanism having computing devices or multiplication tables for computing the units and tens values of a partial product separately, said devices arranged to be controlled jointly and simultaneously by the multiplicand and multiplier for effecting a quick method of multiplication.

With these and incidental objects in view, the invention includes certain novel features of construction and combinations of parts, the essential elements of which are set forth in appended claims, and a preferred form or embodiment of which is hereinafter described with reference to the drawings which accompany and form a part of this specification.

In said drawings:

Figs. 1 to 8 inclusive are tables explaining the principle of operation of the machine of the present invention.

Fig. 9 is a diagrammatic perspective view for use in explaining the principle of operation of the present machine.

Figs. 10A and 10B together comprise a side view of the accounting machine and a sectional view of the multiplying mechanism taken along lines 10-10 of Figs. 11C and 12C with certain parts omitted for clearance.

Figs. 11A, 11B, and 11C combine to constitute a top view of the multiplying mechanism.

Figs. 12A, 12B, and 12C together comprise a sectional view of the multiplying mechanism.

Fig. 13 illustrates the mechanism for coupling the accounting machine and the multiplying mechanism to the main driving mechanism, the lower portion of the figure being a view along line 13-13 of Fig. 14.

Fig. 14 is a cross section of the coupling device illustrated in Fig. 13.

Fig. 15 is a plan view of a part of the mechanism shown in Fig. 13.

Fig. 16 is a detail view of the cam and associated lever for releasing the multiplication key shown in Fig. 13, and is a sectional view taken along line 16-16 of Fig. 14.

Figs. 17A and 17B combine to form a cross sectional view of the multiplying mechanism along line 17-17 of Figs. 11B and 12B and illustrate the connection between the accounting machine and the multiplying mechanism.

Fig. 18 is a cross sectional view of the multiplying mechanism taken along line 18-18 of Fig. 12A.

Fig. 19 is a plan view of a part of Fig. 18, showing the mechanism for setting up and clearing the multiplicand numerals.

Fig. 20 is a section along line 20-20 of Fig.

19, showing in detail part of the multiplicand clearing mechanism.

Fig. 21 is a detail view of the rack and associated gears for clearing the multiplicand numerals.

Fig. 22 is a view partly in section along line 22-22 of Fig. 18, showing a part of the mechanism for computing the units values of the partial products.

Fig. 23 is a view, partly sectioned, along line 23-23 of Fig. 18, and shows a part of the mechanism for computing the tens values of the partial products.

Fig. 24 is a plan view of a part of Fig. 18, showing a portion of the mechanism for selecting the units partial product computing devices or multiplication tables.

Fig. 25 is a detail view of the racks for setting up the multiplicand in relation to the units and tens partial product computing devices.

Fig. 26 is a longitudinal sectional view of the mechanism for transferring the multiplicand and multiplier from the keyboard of the accounting machine into the multiplying mechanism and for transferring the complete product from the multiplying mechanism to the accounting machine.

Fig. 27 is a diagrammatic view showing in detail the internal gear mechanism of Fig. 26.

Fig. 28 is a section along line 28-28 of Fig. 18, showing in detail a part of the mechanism for selecting the tens multiplication tables.

Fig. 29 is a chart illustrating the method of transferring the multiplicand and the multiplier from the accounting machine into the multiplying mechanism and for transferring the complete product from the multiplying mechanism into the accounting machine.

Figs. 30A and 30B together form a diagrammatic sectional view, most of which is taken along line 30-30 of Figs. 17A and 17B and illustrates the mechanism for controlling the drive of the multiplication tables.

Fig. 31 is a chart showing the development of the control cylinder for the mechanism shown in Figs. 30A and 30B.

Fig. 32 is a detail view of the reset gearing for the control cylinder shown in Figs. 17A, 17B, and 31.

Fig. 33 is a development diagram of the restoring cylinder for a part of the mechanism shown in Figs. 30A and 30B.

Fig. 34 is a development diagram of another restoring cylinder shown in Figs. 30A and 30B.

Fig. 35 is a cross sectional view of the product accumulator.

Fig. 36 is a development diagram of the groove in the drum for shifting the control cylinder laterally.

Fig. 37 is a development diagram of the groove in the shifting drum for the product accumulator.

Fig. 38 is a development diagram of the groove in the drum for rocking the product accumulator into and out of engagement with its actuators.

Fig. 39 is a development diagram of the groove in the cylinder for resetting the multiplicand entering pinions.

Fig. 40 is a diagrammatic sectional view taken along line 40-40 (Fig. 35), showing the product accumulator and other mechanism associated therewith.

Fig. 41 is a detail view of the mechanism for controlling the denominational shift of the product accumulator.

Fig. 42 is a left angle projection of the mechanism shown in Fig. 41.

Fig. 43 is a sectional view of the tens transfer mechanism of the product accumulator taken along line 43—43 (Fig. 35).

Fig. 44 is an enlarged detail view of the gears for controlling the rotation of the units multiplication tables.

Fig. 45 is a left angle sectional view of the mechanism shown in Fig. 44.

Fig. 46 is a detail view of the cams and cam lever for controlling the engaging and disengaging of the multiplier storage wheels.

Fig. 47 is a detail view of the cams and lever for controlling the engaging and disengaging of the transmitting segments.

Fig. 48 is a detail view of the cams and associated lever for controlling the entering of the multiplicand.

Fig. 49 is a detail view of the cams and associated lever for controlling the actuation of the units multiplication tables.

Fig. 50 is a detail view of the cams and lever for controlling the transfer mechanism.

Fig. 51 is a detail view of the cams and associated lever for controlling the engaging and disengaging of the product accumulator during the six multiplying operations.

Fig. 52 is a detail view of the cams and lever for controlling the engaging and disengaging of the product accumulator in resetting operations.

Fig. 53 is a detail view of the cams and cam lever for controlling the resetting of the product accumulator.

Figs. 60 to 70 inclusive are illustrations of a modified form of the invention.

Figs. 71A and 71B form a timing chart showing when the various elements are operated during the operations involved in performing a problem of multiplication.

GENERAL DESCRIPTION

As brought out briefly hereinbefore, the subject of the present invention is a multiplying attachment or mechanism for accounting machines, having a maximum multiplying capacity of a multiplicand with eight digits and a multiplier with six digits. Two of the digits in each of the factors may be decimals, such as tenths and hundredths of dollars, and the maximum multiplying capacity of the machine requires that the product accumulator have a capacity of four decimals and ten whole numbers. However, in the final recording of the product, two of the deci-

mals are eliminated, thus leaving a final product of two decimals and ten whole numbers.

To perform a problem of multiplication in the novel mechanism requires nine operations, the first operation being used to introduce the multiplicand and the second operation being used to introduce the multiplier, after which the machine functions automatically through six multiplying cycles to multiply the multiplicand by each of the six digits in the multiplier, and finally, after the multiplying operations, an additional operation takes place automatically, in which the product is printed.

As previously stated, the partial product method of multiplication is employed. There are a tens partial product computing device or multiplication table for each order or digit of the multiplicand, except the lowest order, and two units partial product computing devices forming multiplication tables for each order or digit of the multiplicand, in which multiplication tables the tens and units values of each partial product are stored. After the partial products are selected, they are accumulated in a product accumulator, which is cleared at the end of the six multiplying operations to transfer the complete product from the multiplying mechanism to the accounting machine, where said product is registered and recorded.

Figs. 1 to 8 are tables illustrating the method of multiplication used in the present machine. Fig. 1 shows all the possible partial products from 1 times 1 up to 9 times 9. However, in the short method of forming partial products employed in the present machine, all the above values are not necessary, and in Fig. 2 are shown, in horizontal rows 1 and 4, the units values used in each of the two sets of multiplication tables for the units, and in Fig. 3, in horizontal rows 2 to 9, are shown the tens values as they are figured in each of the tens multiplication tables.

The multiplication tables are composed of wheels having a varied number of teeth, and Fig. 4 shows, in the hatched fields thereof, the number of teeth in each of the units multiplication tables for the horizontal row 1 (Fig. 2), and Fig. 5 shows, in the hatched fields thereof, the teeth in the wheels of each of the other units multiplication tables as represented by the horizontal row 4 (Fig. 2). The hatched fields in the vertical rows 2 to 9 of the table (Fig. 8) represent the teeth in the wheels of each of the tens multiplication tables.

With the aid of the two sets of units multiplication tables (Figs. 2, 4, and 5), it is possible, as will be seen from studying Fig. 6, to obtain all the possible units values by the algebraic composition of the values of rows 1 and 4, either in a positive or negative sense or in both a positive and negative sense. For example, if the digits 1 to 9 of the multiplicand are allotted to the nine vertical rows and the multiplier digits 1 to 9 are allotted to the nine horizontal rows, it is obvious that to each digit of the multiplicand belong three multiplication tables, two for the units and one for the tens, the manner in which the desired units and tens values are obtained from these tables depending upon the value of the digits of the multiplier. Thus, in the present adaptation, it is the duty of the multiplicand to select the proper wheels of the multiplication tables and it is the duty of the multiplier to govern the manner in which these tables are actuated, as will be brought out fully hereinafter.

As illustrated in Fig. 6, this control is effected

in such a way that for the multiplier digit one, only the selected values of row 1 are to be transferred in the positive sense; for the multiplier digit 2, the selected value of row one twice in the positive sense; for the multiplier digit 3 the selected value of row one in the negative sense and the value of row 4 in the positive sense, or 4 minus 1; and so on. The table of Fig. 7 shows which of the two multiplication tables corresponding to horizontal rows 1 and 4 (Fig. 2) are employed each time, whether in the positive or the negative sense, and whether they are to be actuated once or twice. The values so obtained correspond to the units values or partial products desired each time, and may be transferred by suitable means to the product accumulator to form the complete product, which is then transferred to the accounting machine, as will be described later.

To give an example of obtaining the units values of a partial product according to the tables in Figs. 2 and 6, let us take a problem containing a multiplicand digit 4 and a multiplier digit 7. The multiplicand digit 4 determines that the fourth vertical row from the left in the tables 2 and 6 will be selected. According to Fig. 6, the multiplier digit 7 determines that the selected multiplication table having values equal to those of row 1 (Figs. 2 and 6), with its four effective teeth as shown in Fig. 4, is moved once in the positive direction and the selected multiplication table having values equal to those of row 4 (Figs. 2 and 6), with its six effective differential teeth (Fig. 5), is operated once in the negative direction. The algebraic addition of the movements resulting from the effective teeth of these two selected multiplication tables gives the value minus 2 (see the field at the convergence of the fourth vertical and seventh horizontal columns, Fig. 6), which, when set on a 10-tooth storage wheel, corresponds to plus 8. In resetting the storage wheel to zero, the units value 8 of the product is obtained.

As previously stated, the table of Fig. 3 contains the tens values of all partial products, and likewise in this case the vertical rows are allotted to the multiplicand digits 1 to 9 and the horizontal rows to the multiplier digits 1 to 9. Each multiplicand digit 1 to 9 has a vertical row of the multiplication table assigned thereto. Each of these rows is provided with a differential tooth in that position where the tens digit of the respective row is increased by one, which is indicated by the hatched field in the table of Fig. 8. Likewise in this case it is the function of the multiplicand to select the proper wheels of the multiplication table required each time, whereas the multiplier determines the extent of movement imparted to said wheels. In figuring the tens partial product of the above example, 7 times 4, the multiplicand digit 4 selects the portion of the multiplication table corresponding to the fourth vertical row of Fig. 8 and the multiplier digit 7 causes the movement of the multiplication table of seven steps. Tracing the vertical row 4 of Fig. 8 to where it converges with the horizontal row 7, we find that two teeth of this multiplication table become effective, whereby the tens value 2, requisite for this problem, is obtained.

In order further to clarify the system of multiplication employed by the machine of this invention, the mechanism shown in Fig. 9, which shows in diagrammatic form the mechanism for multiplying a single digit by another single digit,

will now be described. The time of operation of the various parts is also shown in Figs. 71A and 71B. The reference numbers of the different parts of the diagrammatic view (Fig. 9) correspond to those of similar parts in the true views of this mechanism, even though in some cases the parts of the modified form do not conform in shape and position to the corresponding parts of the true views.

10 Before multiplication can be effected, it is necessary to enter the digits of the multiplicand and the multiplier into the multiplying mechanism. The multiplicand is entered first (Fig. 71A), and, prior to this entry, the shaft 239 (Fig. 9), is shifted toward the right to move a beveled pinion 238 integral therewith into engagement with a companion pinion 237 connected by a sleeve 1237 to a gear 235, said sleeve 1237 being free on a shaft 236. The gear 235 meshes with the external teeth of an external-internal ring gear 234, the internal teeth of which are engaged by a pinion 233 fast on a shaft 232, which shaft is connected, by a pinion 231 similar to 233, to the internal teeth of a gear 222, which is similar in every respect to the gear 234. The gear 222 is in turn connected to the differential mechanism of the corresponding denominational order of the accounting machine.

30 The multiplicand digit is set up on the keyboard of the accounting machine, and, through the gears 222 and 234, 235, 237, and 238, the shaft 239 is positioned commensurate with the multiplicand. Integral with the shaft 239 is a long pinion 260, the teeth of which are constantly in mesh with a rack 265 secured to an arm 266, which is slidably mounted on a stationary shaft. The arm 266, at the lower end thereof, carries a gear 268 adapted to cooperate with the nine wheels of the units multiplication tables 271 and 272 secured respectively on shafts 355 and 415. Rotation of the shaft 239, by means of the pinions 260, in cooperation with the rack 265, positions the gear 268, with relation to the multiplication tables 271 and 272, in proportion to the value of the multiplicand. The teeth of the pinion 260 also mesh with the teeth of a rack 261 connected to an arm 262 slidably mounted on a stationary shaft. An upward extension of the arm 262 carries a gear 264 adapted to cooperate with the eight wheels of a tens multiplication table 273 secured on a shaft 350, and consequently the gear 264 is positioned with relation to the tens multiplication table, in proportion to the value of the multiplicand.

55 After the gears 268 and 264 have been positioned, as explained above, the shaft 239 is shifted toward the left to disengage the pinion 238 from the pinion 237, thereby disconnecting the multiplicand setting mechanism from its control by the accounting machine differential actuator.

The tens multiplication table 273 is an embodiment of all the tens values of all the partial products indicated in Fig. 3, and the number and arrangement of the differential teeth on the eight wheels of this table are indicated in the shaded portions of the vertical columns of Fig. 8. The units multiplication tables 271 and 272 correspond respectively to the horizontal rows 1 and 4 of Fig. 2, and the respective wheels thereof are provided with differential teeth, as illustrated by the shaded portions of the vertical columns of Figs. 4 and 5, respectively.

70 After the multiplicand has been entered, the

machine comes to rest and the multiplier is then set up on the accounting machine keyboard, after which machine operation is initiated, and during this operation (Fig. 71A) the ring gear 222 (Fig. 9) is positioned in proportion to the value of said multiplier. While the ring gear 222 is being thus positioned, a corresponding multiplier storage wheel 301 is engaged therewith and is also positioned in proportion to the multiplier, after which the storage wheel 301 is disengaged from said gear 222 and engaged with a gear 316. The gear 316 is operatively connected to a control cylinder 330, slidably and rotatably mounted upon a shaft 320, and after the storage wheel 301 is engaged with said gear 316, said storage wheel is reset to zero to position said gear and the cylinder 330 in proportion to the value of the digit of the multiplier.

The circumferential surface of the cylinder 330 has thereon three sets of shifting projections 411a, 411b, 351a, 351b, and 394, and depending upon the extent of rotation of said cylinder 330, one or more of these groups of shifting projections are brought into operative alignment with their respective studs 412, 352, and 393. The studs 412, 352, and 393 are carried respectively by arms 413, 353, and 392, shiftably mounted upon a stationary rod. The shifting projections 411a and 411b, in cooperation with the stud 412, control the drive of the units multiplication table 272, the wheels of which have variable numbers of teeth as shown by the values in the horizontal row 4 of Fig. 6, and said projections determine, according to the plus or minus sign marked in the right-hand vertical row of Fig. 7, whether this multiplication table is to be actuated or not, and whether in the positive or negative direction. The projections 411a and 411b are arranged in two planes on either side of the stud 412 and when the cylinder 330 is positioned angularly in proportion to the multiplier digits 3, 4, or 5 (see the right vertical row of Fig. 7 and Fig. 31) the projection 411b is opposite the stud 412 and when the cylinder is positioned according to the multiplier digits 6 or 7, the other projection 411a is to the right of said stud.

After the cylinder 330 is positioned in proportion to the multiplier digit, as explained above, said cylinder is shifted axially on the shaft 320 first to the right, then to the left, and then back to its normal position as here shown. If, during this lateral shifting of the cylinder 330, the shifting projections 411a or 411b engage the stud 412, the arm 413 is shifted in unison with said cylinder to engage the proper one of two beveled reversing gears 421 or 422 with their driving gear 423. A forked end of the arm 413 engages an annular groove in a sleeve slidable upon the shaft 415 but not rotatable thereon, said sleeve being integral with the beveled gears 421 and 422. The beveled gear 423 is connected to a companion gear 424 which meshes with a gear 426 secured on the shaft 250, upon which is also fixed a gear 428 connected to a driving mechanism. If the gear 422 is connected with the gear 423, the shaft 415 is driven in a clockwise direction and if the gear 421 is connected with said driving gear 423, said shaft is driven in a counter-clockwise direction, and as the units multiplication table wheels 272 are secured on said shaft 415, they are consequently driven in unison therewith.

The shifting projections 351a and 351b on the cylinder 330 control the direction of rotation of the shaft 355 and the units multiplication table

271 which is secured thereon, said multiplication table 271 having teeth corresponding to the values shown in the #1 horizontal row of the table (Figs. 2 and 6). Like the projections 411a and 411b, the projections 351a and 351b straddle the stud 352 and, according to the middle vertical row of Fig. 7, the projections 351a are positioned opposite the stud 352 for the multiplier digits 1, 2, 5, and 7, and the projections 351b are positioned opposite said stud for the multiplier digits 3, 8 and 9. The stud 352 is mounted in a bent-over portion of the arm 353, slidable on the stationary shaft, which also supports the arm 413, and the downward extension of said arm 353 is bifurcated to fit an annular groove in a sleeve 354, slidable on the shaft 355 but not rotatable thereon. The sleeve 354 has integral therewith companion beveled reversing gears 385 and 386, which cooperate with a gear 387 connected to a gear 388, which meshes with a driving gear 389. The gear 389 has a hub which is secured on a shaft 390 and said hub has therein clutch cuts which are engaged by tenons of a sleeve 391 shiftably supported by the shaft 390 and carrying a gear 401 which normally meshes with a gear 403 secured on a drive shaft, upon which is also secured a drive gear 404, by means of which the drive shaft is rotated clockwise as indicated by the arrow.

20 Lateral shifting movement of the cylinder 330, as explained above, depending upon the value of the multiplier, may cause either the projection 351a or 351b, in cooperation with the stud 352, to shift either the beveled gear 385 or 386 into engagement with the gear 387, and when the gear 401 is in mesh with the gear 403, as here shown, the shaft 355 and the units multiplication table 271 secured thereon will be driven either a clockwise or a counter-clockwise rotation, depending upon which of the reversing gears is engaged with the gear 387.

25 By referring to the tables of Figs. 6 and 7, it will be seen that when the multiplier values are 2 or 8 it becomes necessary to transfer the values of row 1 twice instead of once, as is the case with the other of the multiplier values; consequently it is necessary that the shaft 355 be capable of rotating once or twice, as the case demands. The sleeve 391 of the gear 401 has therein an annular 30 groove, which is engaged by a forked downward extension of the arm 392, slidably mounted upon the shaft which also supports the arms 413 and 353, and the upper end of said arm 392 carries the stud 393 which cooperates with the shifting projections 394, one of which is located in relation to the numeral 2 and the other in relation to the numeral 8 (Fig. 31). The shifting projections 394 are located to the right of the stud 393; consequently when one of these projections 35 is opposite said stud, shifting movement of the cylinder 330 causes said projection, in cooperation with said stud 393, to shift the arm 392 and the gear 401 toward the left to move said gear 401 out of engagement with the gear 403 and into engagement with a companion gear 402, which, instead of driving the shaft 355 one revolution, drives it two revolutions in a clockwise or counter-clockwise direction, depending upon which of the reversing gears 385 or 386 is engaged with the gear 387. The units multiplication tables 271 and 272 are thus rotated according to the multiplier numeral set up on the keyboard, and the transferring gear 268, which, as previously stated, was moved in proportion to the multiplicand digit to select wheels

35 40 45 50 55 60 65 70 75

of the multiplication table, is rotated by the teeth of the wheels of said multiplication tables 271 and/or 272 in the proper direction, and transfers the resulting movement to a ten-tooth long pinion 471, which at this time is engaged with the gear 268. The resulting movement of the pinion 471 corresponds to the desired units value of the product and may be transferred to a product accumulator by moving said pinion out of engagement with the gear 268 and into engagement with a gear 472 fast on a shaft 470, said gear 472 being in mesh with the external teeth of the units ring gear 234, which is connected by the pinions 233 and 231 and the shaft 232 to the units ring gear 222, which is in turn connected to the corresponding order of the product accumulator.

As previously stated, the tens value of the partial product is obtained by means of the tens multiplication table 273 (Fig. 9), which is operatively connected by gears 348, 347, 346, and 345 to the control cylinder 330. When the cylinder 330 is positioned in proportion to the value of the multiplier digit, the shaft 350 and the tens multiplication table 273 are rotated in proportion to said multiplier digit. The transfer gear 264, which has previously been positioned in proportion to the digit of the multiplicand to select a wheel of the multiplication table, is rotated by the wheel of the tens multiplication table 273 in accordance with the tens value of the partial product. The tens value of the partial product is transferred from the pinion 264 to a long pinion 481, which is constantly in mesh therewith, and from said long pinion to a gear 1481 integral therewith, to a tens ring gear 234 and from said gear to a corresponding tens ring gear 222, which is connected to the tens order of the product accumulator.

It is believed that the foregoing general description, given in connection with the diagrammatic view (Fig. 9), will be helpful in promoting a better understanding of the detailed description which follows immediately.

DETAILED DESCRIPTION

Accounting machine

As previously stated, the multiplying mechanism, which is the subject of this invention, is attached to the base of a standard type of accounting machine shown best in Fig. 10A. As the accounting machine serves only the purpose of introducing the multiplicand and the multiplier, and of registering and recording the product computed by the multiplying mechanism, it is believed that a brief résumé of the mechanism of the accounting machine and its operation will be sufficient. The details of this mechanism can be found in the patents referred to at the beginning of this specification.

The mechanism of the accounting machine is supported by and between two side frames secured to a machine base to which the multiplying mechanism is attached. The keyboard of the accounting machine comprises, in this particular adaptation, eight rows of amount keys 201, a multiplication key 202, and a machine starting bar 203. Each of the amount keys 201 carries a square stud 205, which, upon depression of said amount keys, is moved into the path of the corresponding one of a series of graduated steps on the top surface of actuator racks 204 mounted to slide horizontally upon two transverse bars supported by the machine framework. The rear-

wardly disposed ends of the actuator racks 204 have on the upper and lower surfaces thereof teeth adapted to cooperate with the corresponding denominational orders of the accumulator wheels, which are actuated thereby. The machine may have from one to six accumulators, including an adding and subtracting accumulator, depending upon the requirements of the business system in which the said machine is used.

Each of the racks 204 has a vertical slot which cooperates with a stud 1207 in a downwardly extending segmental portion of a reducer arm 206, mounted on a shaft 1208, supported by the side frames. A spring 1209, tensioned between the reducer arm 206 and the cross bar of a leading frame 632, mounted on the shaft 1208, normally maintains an enlarged portion of said reducer arm 206 in yielding contact with the cross bar of said leading frame. A rearward extension of the reducer arm 206 is connected by a link 1210 to a printing sector 1211 for this particular denomination, which sector 1211 is pivotally mounted on an operating arm 1212. The printing sector 1211 is adapted to cooperate with a platen roll 1213, mounted in a traveling carriage, which in turn is mounted for horizontal shifting movement upon the case which encloses the mechanism of the accounting machine.

Upon operation of the accounting machine, which is initiated by depression of the starting bar 203, the shaft 1208 and leading frame 632 are rocked first counter-clockwise, causing said leading frame, by means of the spring 1209, to yieldingly carry the reducer arms 206 counter-clockwise in unison therewith, and in turn said reducer arms, by means of the studs 1207, shift the actuator racks 204 rearwardly (Fig. 71A). The rearward movement of the actuator racks 204 continues until the proper one of the graduated steps on the top surface thereof comes in contact with the studs 205 of the depressed amount keys 201, whereupon rearward movement of said racks is terminated and the leading frame 632 completes its rearward movement, stretching the springs 1209.

This positions the actuators 204 and the reducer arms 206 in proportion to the depressed amount keys, and said reducer arms in turn, by means of the links 1210, position the printing sectors 1211 for the various orders commensurate with the value of the depressed amount keys. After the printing sectors 1211 have been thus positioned, the actuating arms 1212 are released for clockwise operating movement, thereby causing said printing sectors to strike the platen 1213 a hammer-like blow to record the value of the depressed amount keys upon record material wound around said platen roll.

In adding operations, prior to return movement forwardly of the actuator racks 204, the wheels of the selected accumulator or accumulators are engaged therewith, whereupon return movement clockwise of the leading frame 632 carries the actuators 204 forwardly to normal or zero position, to enter the amount represented by the depressed amount keys 201 in the wheels of the selected accumulators. In subtract operations, the wheels of the add-subtract accumulator are engaged with the actuators 204 prior to their initial movement rearwardly, and upon such movement thereof, are reversely rotated to subtract from said wheels the amount represented by the depressed amount keys. In total printing operations, the wheels of the selected accumulator are engaged with the actuators 204

prior to their initial movement rearwardly, and upon such movement are reversely rotated to position said actuators 204 in proportion to the amount standing on said accumulator wheels. Prior to return movement forwardly of the actuators 204, the wheels of the selected accumulator are disengaged therefrom, and consequently remain in a zeroized condition. In sub-total printing operations, the wheels of the selected accumulator, instead of being disengaged from the actuators 204 at the terminus of their initial movement rearwardly, remain in engagement therewith, and upon return movement forwardly of said actuators, are restored to their original positions.

Framework of the multiplying unit

The various parts of the multiplying mechanism are supported by and between main frames 1214 and 1215 (Figs. 10B, 11, 12, and 19), an intermediate frame 1216, and a sub-frame 1217, secured to a top plate, which in turn is secured to the base of the accounting machine. The frames 1214, 1215, 1216, and 1217 are connected by a front frame 1218 and various other cross frames, bars, and rods. Likewise these frames are supported by a base plate 1219.

A complete multiplying operation, including the entering of the multiplicand and the multiplier, the multiplying of the multiplicand by each digit of the multiplier, and the registering and recording of the complete product, requires one complete rotation of a main shaft 210 for the multiplying mechanism (Figs. 10, 11, and 12), said rotation being made up of six partial rotations. During this complete revolution of the main shaft 210, the nine operations required to effect a complete problem of multiplication are performed by the multiplying mechanism and, when necessary, by the accounting machine. As previously brought out, the multiplicand and the multiplier are entered in the accounting machine and the multiplying mechanism during the first and second partial rotations of the shaft 210. During the next three partial rotations of shaft 210, the six multiplying operations take place, so that the multiplicand is multiplied by each of the six digits of the multiplier, and in the final partial rotation of shaft 210, the ninth operation takes place, in which operation the complete product is transferred from the multiplying mechanism to the accounting machine, where it is registered and recorded.

The timing chart shown in Figs. 71A and 71B is divided into six sections, each of which corresponds to one of the partial rotations of the shaft 210.

Operating mechanism

The machine is operated by a conventional type of electric motor and is released for operation by depression of the starting bar 203 (Fig. 10), which engages the clutch mechanism and closes the circuit to the motor, so that a shaft 650 (Figs. 10B, 11, and 12), directly connected to the motor, is actuated.

The shaft 650 is provided with teeth 651 which mesh with a gear 652 mounted on the main shaft 210 journaled in the frames 1214, 1215 and 1217, said gear 652 having a pin 653 (Figs. 13 and 14) which carries a coupling pawl 654. When the machine is in home position, the coupling pawl 654 engages a notch 655a of a disk 655 rigidly connected to a gear 656 by a hub 656a free on the shaft 210. The gear 656 (Figs. 11 and 12)

meshes with a gear 657, free on the motor shaft 650, from which gear 657 the drive of the accounting machine is derived in any suitable manner.

5 The coupling pawl 654 has a roller 659 (Figs. 13 and 14) which engages a cam groove 660a in the outside face of a gear 660 loosely mounted on the shaft 210. Normally the gear 660 is connected to the gear 652 by means of a two-part coupling 10 pinion 661 (Figs. 13 and 14), and is actuated in unison with said gear. The coupling pinion 661 is free on a stud carried by a two-armed lever 662 (Figs. 13 and 15) pivoted on a stud 663 in the frame 1217. The other arm of the lever 662 carries a two-part coupling pinion 664, one part of which is in the plane of the gear 652, and the other part in the plane of a gear 665 secured to the shaft 210. The lever 662 is connected by a link 666 (Fig. 13) to a lever 667 pivoted on a stationary stud 668. A camming slot in the lever 667 engages a stud 669 in a slide 670 shiftably supported by means of slots therein in cooperation with two stationary studs 671, and normally held in its upper position by a spring 672. The stem of the multiplication key 202 is mounted on the side of the slide 670 so that it can be shifted in relation thereto, said stem being guided by a slot therein in cooperation with the pin 671 and by a pin 675 in said stem, in cooperation with a slot in the slide 670. The pin 675 carries a pawl 676 having a bent portion 678 which, under the action of a spring 677, is normally engaged with a recess 679 in the slide 670, thereby coupling said slide to the stem of the multiplication key 202.

20 Under the action of a spring 681, one arm of a lever 682, free on a stationary stud, is yieldingly retained in contact with a bent over extension 670a of the slide 670. The lever 682 is connected by a link 683 to a lever 684 (Figs. 14 and 16) pivoted on the stud 663. The lever 684 has a roller 685 lying in the plane of revolution of a cam disc 686 fast on the shaft 210.

25 Upon depressing the multiplication key 202, the pawl 676 carries along slide 670 (Fig. 13) until, under the action of the spring 681, a notch in the lever 682 engages the extension 670a, thus retaining the slide 670 in its lower position. The movement of the lever 682 causes the arm 684 to rock clockwise until its roller 685 contacts the periphery of the cam 686. At the same time, downward movement of the slide 670 causes the stud 669 to rock the lever 667 and the lever 662 counter-clockwise. By this rocking movement, the coupling pinion 664 is disengaged from the gears 652 and 660, and the coupling pinion 664 is brought into mesh with the gears 652 and 665. Whichever one of the pinions 661 or 664 is disengaged, is secured against rotation by its locking pawl 688, and when the pinion 661 is disengaged, a locking piece 690 (Figs. 13, 14 and 15), attached to the lever 662, engages the teeth of the gear 660 to hold said gear locked against rotation.

notched disc 655. Through the gears 656 and 657 (Figs. 11 and 12), this movement of the disk 655 is transmitted to the drive of the accounting machine.

Shortly before the first partial or one-sixth rotation of the shaft 210 is terminated, one of two nodes of the cam 686 (Figs. 13 and 16) acts on the roller 685 and raises the lever 684 to disengage the lever 682 from the extension 670a of the slide 670. The spring 672 restores the slide 670 and the multiplication key 202 into their upper initial position which causes the lever 667 to disengage the coupling pinion 664 and to reengage the pinion 661. The motor bar 203 is also restored and the motor circuit is broken. At this time, the accounting machine has finished one operation and is stopped in its normal position. Also, the shaft 210, which drives the multiplying mechanism, is stopped after the first partial rotation.

The multiplication key 202 is again depressed to enter the multiplier, thereby causing the arm 662 with the coupling pinions 661 and 664 to be rocked as before to disengage the pinion 661 and engage the pinion 664, and thereby the gear 652 is coupled with the gear 665, secured to shaft 210, whereas the gear 660 is held locked. Depression of the motor bar 203 releases the machine for operation, whereupon the coupling pawl 654 of the gear 652 carries along the disc 655, thus driving the accounting machine. In addition, the gear 652, through the pinion 664 and gear 665, rotates the shaft 210, thus actuating the multiplying mechanism to enter the multiplier.

After a further partial rotation of the gear 652, the coupling pawl 654 (Figs. 13 and 14) is lifted by an ascending portion of the cam groove 660a, and thereby the gear 652 and the disc 655 are disengaged. At the same time, a bevelled edge of a stop piece 694, attached to the gear 652, contacts an upper arm of a locking lever 695 mounted on the gear 660, which is at rest at this moment, and rocks said lever clockwise to move an extension 696 thereof into the path of one of two pins 697 fast in the disc 655, to prevent said disc 655 from moving further. Thereby the accounting machine which, during this second partial rotation of the gear 652, has again performed a complete operation, is disengaged from the driving mechanism and is held in its normal position. As the disc 686 (Fig. 16) has no node at this position, the multiplication key 202 and the motor bar 203 are not released and the machine operation is therefore not interrupted and the shaft 210 is rotated during the remaining partial rotations without any further interruption. At the end of the last partial rotation of the shaft 210, the second node of the disk 686 causes the release of the multiplication key 202 and the motor bar 203, thereby terminating operation of the machine after a full rotation of the shaft 210 which drives the machine through a complete multiplication.

After the multiplying operations have been completed and after the shaft 210 has completed five-sixths of its rotation, the stop block 694 releases the locking lever 695 which, under the tension of its spring 698, is moved out of the path of the pin 697. At the same time, the coupling pawl 654 is moved, by a descending portion of the cam groove 660a, into a second notch 655b of the disc 655, so that the actuating mechanism of the accounting machine is again coupled to the gear 652 for the last partial rotation of said disc and shaft 210.

Eight setting segments 208 (Figs. 10A and B, 11A, B and C, and 17A and B) and six other segments 208a, 208b and 208d, the function of which will be explained later, are loosely mounted on a rod 209 carried by two arms 211 loose on the main shaft 210. One of said arms 211 has two rollers 212, 213 (Figs. 12B and 47) cooperating with a cam disc pair 215, 216 mounted on the shaft 214. These two cam disks are rigidly connected to a gear 217 which, through gears 218, 219 free on a shaft 220, is connected to a gear 221 fast on the main shaft 210. The main shaft 210 is given, in the above mentioned manner, a full clockwise rotation during the whole multiplying operation, and performs during the multiplicand-entering operation one-sixth of a rotation in the clockwise direction.

The gears 221 and 219 form an intermittent drive which, in the first one-sixth rotation of the shaft 210, after the racks 204 have been positioned (Fig. 71A), communicates a half rotation to the cam discs 215, 216 and, after the racks 204 are restored, another half rotation. The cam discs 215, 216 (Fig. 47) are so shaped that, when in initial or normal positions, they hold the arms 211 and the shaft 209 in a position where the setting segments 208, 208a, 208b, and 208d are out of mesh with the ring gears 222, 222a, 222b, 222d (Figs. 10A and B, 11B, and 17A and B), one of said ring gears being allotted to each one of the fourteen setting segments 208, 208a, 208b and 208d. The sixteen ring or external-internal gears are part of a transmitting mechanism for the multiplicand, multiplier and product, which is described below and which is located on a stationary rod 223.

During the setting movement (Fig. 71A) of the differential racks 204 and the corresponding eight setting segments 208, the latter are not in mesh with the corresponding ring gears 222. After the gear segments 208 are positioned in accordance with the introduced multiplicand, the shaft 209 and the gear segments 208 are rocked so as to engage the latter with the outside teeth of the ring gears 222.

Then the actuator racks 204, as well as the setting segments 208, are positively restored in the clockwise direction. This restoring movement of the segments 208 is obtained by means of a special driving device which becomes active simultaneously with the restoring of the racks 204. The driving device comprises a driving gear 224 (Fig. 12B) secured to the main shaft 210 and which causes a gear 226 (Figs. 17A and 17B) mounted on the shaft 225 to make one revolution. The gear 226 is integral with a cam 227, the periphery of which cooperates with a rod 228 supported by arms 229 (Fig. 11B) mounted on each side of the segments 208, 208a, 208b and 208d. A spring 230 maintains the rod 228 in contact with the cam 227 (Figs. 10A, 10B, 17A, and 17B). The rod 228 extends under all setting segments 208, 208a, 208b and 208d and, under the action of the cam 227, comes into contact with a protruding surface on the bottom of the setting segments 208. The latter are thus carried to their initial positions and their positioning is transmitted to the corresponding ring gears 222.

70

Multiplicand entering mechanism

The internal teeth of each of the eight ring gears 222 mesh with a pinion 231 mounted on a shaft 232, the other end of which shaft supports a second pinion 233 (Fig. 18) meshing

75

with the internal teeth of one of the eight ring gears 234 (Figs. 9, 11A, 11B, 18, 26, 27, and 29).

The above internal-external ring gears and their connecting pinions and shafts form a well known type of transmission or driving mechanism, which is fully disclosed in United States Patent No. 1,693,279, issued November 27, 1928, to Walter J. Kreider.

Each of the eight ring gears 234 meshes with a related gear 235 (Figs. 18 and 19) loose on a shaft 236 and fast to a corresponding bevelled pinion 237. The pinions 237 are arranged to mesh with corresponding bevelled pinions 238 each secured to one end of a short shaft 239, the other end of each of said shafts 239 having secured thereon a retaining gear 240 (Figs. 19 and 20). Each of the gears 240 cooperates with a resilient retaining pawl 241 mounted on a bar 242, so that the shaft 239 may be retained against unintentional rotation while in its normal disengaged position.

All the shafts 239 are shiftably mounted in holes in two fixed cross bars 243 and 244 secured by brackets to the frames 1215 and 1216 (Figs. 18 and 19), and said shafts are likewise connected to a common shifting bar or beam 245, opposite ends of which are connected to two arms 246 free on a shaft 250 (Figs. 12A, 12B and 18) and connected by a yoke 247. The right arm 246 is secured to one end of a tube 248 free on the shaft 250, and secured to the other end of said tube 248 is a lever 249 (Figs. 12A, 12B and 48) provided with rollers 251 and 252 cooperating respectively with companion plate cams 253 and 254 free on the shaft 245. Operation of the plate cams causes the yoke 247 and the arms 246 to rock, first in the clockwise direction and then back. By this movement the beam 245 shifts all the eight shafts 239 and meshes the bevelled pinions 238 with the bevelled pinions 237.

The time of this engagement is determined by a driving gear 258 (Fig. 12B) secured on the main shaft 210 which, in cooperation with an operating gear and a locking disc 257, constitutes an operating device connected by gears 256 and 255 to the plate cams 253 and 254. This operating device is so arranged as to cause one-half revolution of the cams 253 and 254, in order to cause the rocking movement of the beam 245, before and after the setting movement of the ring gears 234. In this way the bevelled pinions 238 are coupled with the corresponding pinions 237, only during the setting movement of the ring gears 234 and are set commensurate with the value of the introduced multiplicand (Fig. 71A). Therefore, each of the shafts 239 (one shaft is provided for each denominational order) is set proportionally to the value of the multiplicand numeral of the order considered.

Each of the shafts 239 comprises a middle toothed portion 260 (Figs. 18, 19 and 25) which meshes with corresponding toothed parts of two racks 261 (upper) and 265 (lower). The pair of racks of two neighboring shafts 239 are arranged in different planes to avoid interference during their movements (Figs. 18, 19, 24 and 28). The racks 261 and 265 are secured respectively to brackets 262 and 266 slidably mounted respectively on the pairs of shafts 263 and 267. Each of the brackets 262 has an extension supporting a pinion 264, and each of the brackets 266 has an extension supporting a pinion 268, and both of said pinions may be axially shifted by means of the mechanism set forth above.

The mechanism, above described, for entering the multiplicand, works in the following manner.

The multiplicand is set up on the amount keys 201 (Figs. 10A and 10B), and then the multiplication key 202 and the motor bar 203 are depressed. During this operation, the upper part of the machine (called the accounting machine) effects a normal operation, and the main shaft 210 of the multiplying device rotates one-sixth of a revolution. During this operation (Fig. 71A) the actuator racks 204 for the accounting machine are first positioned according to the value of the multiplicand, and the different positions are transmitted to the setting segments 208 by means of the arms 206 and the links 207. After the segments 208 are positioned, the gear 221 (Fig. 12B), secured to the main shaft 210, causes the double-cam 215, 216 to make one-half of a revolution, thus rocking the arms 211 and the rod 209 towards the left (Figs. 10A, 10B and 17A, 17B) in order to carry the setting segments 208 in mesh with the outside teeth of the eight corresponding ring gears 222. Simultaneously, the gear 258 (Fig. 12B), secured on the driving shaft 210, causes the plate cams 253 and 254 to effect one-half of a revolution, and the bevelled pinions 238 of all denominational rows therefore engage the pinions 237 (Figs. 18 and 19).

After achievement of this connection the racks 204 are positively restored to their initial positions by the leading frame 632 (Fig. 10A) and the movements of the racks are transmitted by the segments 208 to the ring gears 222, and then to the ring gears 234, and finally to the shafts 239 (Fig. 18). The restoring rod 228 cooperates with the setting segments at this time to assist the leading frame 632 in returning the various parts to their initial positions. Each shaft 239 in the different orders effects the displacement of the racks 261 and 265, and therefore the lateral shifting of the pinions 264 and 268 (Figs. 11A, 11B, 12A and 12B) and this, towards the right or left, in proportion to the multiplicand figure in each other.

Multiplication tables

Each of the pinions 268 may be shifted in relation to two multiplication tables or bodies 271 and 272, each comprising differential wheels 271₁₋₉ and 272₁₋₉ (Figs. 12A, 12B, 18 and 22). Two of these tables or bodies are arranged opposite each other in each denominational order, so that there is one of each of the tables 271 and 272 and a corresponding pinion 268 for each order. Likewise, there is a pinion 264 for each order, located in the path of a corresponding multiplication table or body 273 (Figs. 11A, 11B, 18 and 23) comprising differential wheels 273₂₋₉, but located in the next higher order in relation to the wheels of tables 271 and 272. The multiplication body 273 cooperating with the pinion 264 of the eighth denominational order belongs therefore to the ninth order (Fig. 11A). In the ninth denominational order, a ring gear 234a is provided which may be coupled through parts 233a, 232a, 231a, with a ring gear 222a (Figs. 26, 27 and 29) and through a setting segment 208a with the rack 204a of the overflow order of the accounting machine.

Fig. 29 is a view showing in diagrammatic form the relation between the setting segments 208, 208a, 208b, and 208d, and the corresponding internal-external ring gears 222, 222a, 222b, and 222d; the relationship between the setting seg-

ments 222 and 222a and the corresponding internal-external ring gears 234 and 234a, the shafts and pinions for connecting these ring gears; the relationship between the multiplication tables and the ring gear 234 and 234a, and the relationship between the product accumulator and the setting segments 222, 222a, 222b, 222c, and 222d.

After the pinions 268 and 264 have been brought in the plane of the wheels of the tables 271, 272 and 273, respectively, corresponding to the multiplicand digits, the second one-half revolution of the plate cams 215, 216 and 253, 254 causes the setting segments 208 to be disengaged from the ring gears 222 and the bevelled pinions 238 to be disengaged from the pinions 237. This completes the operation of entering the multiplicand.

Multiplier entering mechanism

The multiplier is then set up on the amount keys 201 and in the present embodiment the multiplier may comprise at the most six orders. Next the multiplication key 202 and the motor bar 203 (Fig. 10) are depressed. A normal operation of the accounting machine is again initiated, during which the main shaft 210 of the multiplying device effects another one-sixth of a revolution. During this operation (Fig. 71A) as before, the six lower order or right-hand racks 204 are positioned according to the depressed amount keys and the setting segments 208 are coupled with the corresponding ring gears 222, so that during the positive restoring of said racks 204 and segments 208, the value of the multiplier is transmitted to the corresponding ring gears 222 and by them to the ring gears 234 connected thereto.

Multiplier storage wheels

Before the positioning of said ring gears 222 and 234, six multiplier storage wheels 301₁₋₆ (Figs. 12B, 17A, 17B, 71A, and 71B) are carried into mesh with the gears 222 of the six first orders, said wheels being each supported separately by an arm 302 and prevented from unintentional rotation by a resilient retaining pawl 303. The arms 302 are loosely mounted on a shaft 305 and extensions 306 of these arms are provided with rollers 307 and 308 cooperating with companion plate cams 309 and 310 mounted on the shaft 214. Each pair of cams has integral therewith a gear 311 meshing with a gear 312 fast to a pinion 313, which cooperates with a drive gear 314, said driving gears 314₁₋₆ being fast on the driving shaft 210. The toothed portions of the six driving gears 314₁₋₆ are arranged in such a manner that during the partial operation in which the multiplier is set up, all the six plate cams 309 and 310 receive simultaneously half a revolution in the clockwise direction. These pairs of cams are, however, shaped in such a manner that first all arms 306 are rocked in the clockwise direction to bring all six toothed wheels 301₁₋₆ simultaneously in mesh with the ring gears 222, before the positioning movement of the latter. When the ring gears 222 rotate, the wheels 301₁₋₆ are therefore positioned according to the value of the introduced multiplier. After this positioning, all wheels 301 are disengaged from the ring gears 222 under the action of the cams 309 and 310, the retaining pawls 303 holding said wheels in their new positions (Figs. 17A and 17B).

The accounting machine has therefore completed its second operation and is now rendered

inoperative by means of the clutch mechanism already described. On the contrary, the main shaft 210 of the multiplying device effects four further partial revolutions, each time moving one-sixth of a revolution. The first three of these four partial revolutions are provided for the six multiplying operations, as will be described hereafter.

During the next three one-sixth revolutions of the main shaft 210 (Figs. 71A and 71B), the second toothed portions of the wheels 301₁₋₆ become active, but as said toothed portions are graduated angularly with relation to each other, the six cams 309 and 310 are actuated one after the other, beginning with the lowest order. Due to this actuation and due to the shape of the cams 309 and 310, the arms 302₁₋₆ are rocked one after the other in such a way that first the multiplier storage wheel 301₁ meshes with a corresponding toothed wheel 316₁ (Fig. 71A) from which it is disengaged after a given time (Figs. 12B, 17A and 17B). Next the storage wheel 301₂ is engaged with its corresponding toothed wheel 316₂, and so on until all the storage wheels 301 have been coupled with their corresponding toothed wheels 316. The toothed wheels 316₁₋₆ are loosely mounted on a resetting shaft 320, and each of them is permanently in mesh with a corresponding gear 317 secured to a shaft 325. Each of the storage wheels 301₁₋₆ is rigidly connected to two discs 318 and 319, said disc 318 having two teeth, and said disc 319 having a locking part. The discs 318 and 319 cooperate respectively with two toothed and locking discs 321 and 322, secured on the shaft 320, the whole forming a resetting mechanism.

Multiplier control cylinder

During the time the wheels 301₁₋₆ are successively engaged with and disengaged from the wheels 316₁₋₆, the resetting shaft 320 rotates one revolution, by means of a mechanism to be described later, and the storage wheels 301₁₋₆ are therefore, by means of the resetting parts 318, 319, 321 and 322, successively reset to zero (Figs. 71A and 71B). The values on the wheels 301 are then, through the wheels 316, transmitted one after the other to the gears 317 and therefore to the shaft 325. A gear 326 is fast to the righthand end of the shaft 325 and meshes with a long pinion 327 (Figs. 12B and 30A) secured to a sleeve 1330 free on the shaft 320. The long pinion 327 meshes with the teeth of an internal gear 328 secured to the left end of a cylinder 330 free on the sleeve 1330, which is free on the shaft 320.

A pinion 331 (Figs. 12C, 30A, 30B and 58) secured to the left end of the shaft 320 is connected, through an intermediate gear 332 pivoted on a stud 335, to an intermittent driving mechanism comprising gears 333 and 334, the driving gear 334 of which is secured to a sleeve 336 loose on the main shaft 210. The sleeve 336 is connected through gears 337 to 340 with an intermittent driving mechanism comprising gears 341 and 342 (Figs. 12B and 59), the driving gear 342 of which is secured to the shaft 210. The toothed portions of this mechanism are arranged so as to communicate, during each of the third, fourth and fifth 70 partial or one-sixth revolution of the shaft 210, two full revolutions to the sleeve 336. These two revolutions are transmitted to the sleeve 336 by the gears 340, 339, 338 and 337, and the gear 334 thus rotates six revolutions during the three partial revolutions of the shaft 210 comprising the

six multiplying operations. At each of these six revolutions of the sleeve 336, the toothed part of the gear 334, through the gears 333, 332 and 331, causes the resetting shaft 320 to rotate one revolution, and this occurs each time one of the six storage wheels 301₁₋₆ is engaged with the corresponding resetting gearing 318, 319 and 321, 322. The storage wheel which is engaged at the moment is thereby reset and the value obtained, which corresponds to the multiplier figure introduced in this particular order, is transmitted to the shaft 325 by the gears 316 and 317, and then to the cylinder 330 by the gears 326, 327 and 328.

Operation of tens multiplication tables

The sleeve 1330 connects the long pinion 327 to a gear 345 (Figs. 12B, 17A and 17B), and said gear is connected through gears 346 and 347 to a gear 348 (Figs. 11A and 11B) secured to a shaft 350. Also secured to the shaft 350 are the multiplication tables 273 for the tens values of partial products, said tables comprising wheels 273₂₋₉. These tables 273 are located in the different denominational orders of the multiplying mechanism beginning with the second order and extend from the second to the ninth orders. By means of the resetting operation, described above, of the multiplier storage wheels 301₁₋₆, the shaft 350 and the multiplication tables 273 for the tens values of the partial products are rotated in proportion to the value of each multiplier figure introduced.

The cylinder 330 is first positioned proportionate to the value of the lowest order multiplier digit by the first rotation of the reset shaft 320, which resets the first multiplier storage wheel 301₁, after which this storage wheel is disengaged by the cams 309 and 310.

Operation of units digit partial product multiplication tables

The cylinder 330 comprises on its periphery a number of projections 351a and 351b, 394, and 411a and 411b, arranged as per Fig. 31, which is a chart showing the development of the cylinder. The first group of projections 351a and 351b cooperate with a stud 362 and comprise five projections, three of which are located in a plane on the right or upper side of the stud 352 and two in a plane below or on the left of said stud. When the cylinder 330 is in the home position, the projections 351 are so located in relation to the stud 352 that partial rotation of the cylinder of one, two, five, or seven units or divisions brings one of the projections 351a opposite the stud 352, whereas a partial rotation of the cylinder 330 of three, eight, or nine units brings one of the projections 351b opposite the stud 352. The stud 352 (Figs. 17A, 17B, 30A, and 30B) is supported by an arm 353 rotatably but unshiftably mounted on a sleeve 354, which is shiftably but not rotatably mounted on a shaft 355 journaled in the machine framework. An extension of the arm 353 has a stud 356 which is normally in the path of a groove 357 of a cylinder 358 (Figs. 30A, 30B, and 33) secured to a shaft 360. Normally the groove 357 holds the arm 353 and the stud 352 in the middle position as here shown, from which it cannot be shifted.

When the cylinder 330 has been positioned, in the manner described, in proportion to one of the digits of the multiplier, the cylinder 358 is turned from the sleeve 336, by an intermittent driving mechanism including gears 361 to 365 (Figs. 12C, 30A, 30B, and 57), sufficiently to free

the stud 356 from the groove 357 so that the arm 353 may be shifted. After this release, the arm 353 and the sleeve 354 (Figs. 30A and 30B) are held against unintentional shifting by a resilient pawl 366 in cooperation with the center one of three grooves in a sleeve 367 integral with the sleeve 354.

Lateral shifting of the control cylinder

10 After the arm 353 is released, the cylinder 330 is shifted laterally (Figs. 71A and 71B), to couple the shaft 355 to its driving mechanism, as will now be described.

15 A groove in the cylinder 330 is embraced by a shifting arm 371 shiftably mounted on a shaft 370 (Figs. 30A and 30B), and said arm 371 has a roller 372 which engages a groove 373a in a shifting drum 373 fast on a shaft 375. The other end of the shaft 375 carries a pinion 376 connected, through gears 377 to 379, to an intermittent driving mechanism including gears 381 and 382 (Figs. 11C, 12C, and 56), the driving gear 382 of which is secured on the sleeve 336 performing, as brought out above, six revolutions, during the multiplying operations. At 20 each of these six revolutions the gearing in question causes the shaft 375 and therefore the grooved drum 373 to rotate one revolution. The groove 373a is so shaped (Fig. 36) that, for each revolution of the drum 373, the cylinder 330 is first shifted one division downwardly or toward the right, then two divisions upwardly or toward the left, and at last again one division toward the right, into its initial position.

25 When one of the projections 351a or 351b has been positioned opposite the stud 352, the shifting movement of the cylinder 330 carries the arm 353 and the sleeve 354 toward the right or the left, as the case may be. Two bevelled pinions 385 and 386 (Figs. 17A, 17B, 30A, and 30B) are secured to the sleeve 354, and during the shifting of the cylinder 330, one or the other of the bevelled pinions 385 or 386 is brought into mesh with a bevelled pinion 387. The latter is integral with a pinion 388 meshing permanently with a bevelled pinion 389 secured on a shaft 390 journaled in the frames 1216 and 1217. A sleeve 391 is shiftably but not rotatably mounted on the shaft 390, whereas an arm 392 is unshiftably mounted in a groove in said sleeve. The arm 392 has a stud 393 arranged to cooperate with the projections 394 of the cylinder 330 (Fig. 31). These two projections 394 are located in relation to the stud 393 so that a partial rotation of the cylinder 330 of two or eight divisions will 30 position one of these two projections opposite the stud 393. When the cylinder 330 is in one of these two positions, it carries the arm 392 and the sleeve 391 one division downwardly or toward the right. The sleeve 391 is maintained against unintentional shifting in either of its positions by a resilient retaining pawl 396 cooperating with two annular grooves in a sleeve 397 integral with the sleeve 391.

35 A pinion 401 (Figs. 12C, 30A, 30B, 44, and 45), secured to the sleeve 391, is normally in the plane of a toothed disk 402 and after its shifting to the right, is in the plane of a toothed disk 403. These two disks 402 and 403 are rigidly connected by a hub to a gear 404 which is itself operatively connected by an intermediate gear 405 to an intermittent driving mechanism comprising gears 406 and 407 (Figs. 12C and 58). The driving gear 407 of this mechanism is secured to the sleeve 336 and the driving movement

is transmitted in such a way that after each of the six partial shifting movements of the cylinder 330, both toothed discs 402 and 403 make one revolution. The toothed part of the disc 402 (Fig. 58) is so arranged as to cause the sleeve 391 and the shaft 390 to make one revolution when said gear 401 is in its path. The toothed part of the disc 403 is twice as long as that of the disc 402, and when the gear 401 is in the plane of said disc, one revolution of the disc 403 is transformed into two revolutions of the sleeve 391 and the shaft 390. This single or double revolution of the shaft 390, as the case may be, is transmitted, through the bevelled pinions 389, 388, and 387 (Figs. 30A and 30B) to the bevelled pinion 385 or 386, whichever is engaged at the moment, so that the shaft 355 rotates one or two revolutions in a clockwise or in a counter-clockwise direction, as the case may be. As aforesaid, the shaft 355 supports the multiplication tables 271 for the units, said tables comprising differential wheels 271₁₋₉ (Figs. 12A and 18) which, according to the value of the multiplier digits, are not actuated at all or are actuated once or twice in a clockwise or a counter-clockwise direction during the six successive multiplying operations.

The cylinder 330 also has the two projections 411a and 411b, which cooperate with a stud 412 (Figs. 17A, 17B, 30A, 30B, and 31). The projection 411a is located above or on the left of the stud 412 and in such relation thereto that, upon rotation of the cylinder 330 through six or seven divisions, said projection 411a is positioned opposite said stud 412. The stud 412 is supported by one end of an arm 413 rotatably but unshiftably mounted in an annular groove in a sleeve 414, which is in turn shiftable but not rotatably mounted on a shaft 415 journaled in the frames 1214 and 1216. The other end of the arm 413 has a stud 416 which normally engages a groove 417 (Fig. 33) in the cylinder 358, thus holding the arm 413 in the middle position as illustrated in Figs. 30A and 30B. When the cylinder 330 is positioned in proportion to the multiplier digit, the cylinder 358 rotates sufficiently to release the stud 416 from the groove 417. At this moment the sleeve 414 is held against unintentional shifting by a resilient retaining pawl 418 engaged in one of three grooves in a sleeve 419 integral with the sleeve 414.

The axial back and forth shifting movement of the cylinder 330 causes the arm 413 and the sleeve 414 to be displaced one division downwardly or toward the right, if the projection 411a is active, and toward the left if the projection 411b is active. The sleeve 414 supports two bevelled pinions 421 and 422 (Figs. 17A, 17B, 30A, and 30B), one of which is, during the shifting movement of the arm 413, carried into mesh with a bevelled pinion 423 mounted on a stationary support 425 and rigidly connected to a bevelled pinion 424. The pinion 424 is permanently in mesh with a corresponding pinion 426 fast to the shaft 250. Fast on one end of the shaft 250 is a gear 428 connected by a gear 429, free on a stud 430, with an intermittent driving mechanism including gears 431 and 432 (Figs. 12C and 59), the driving gear 432 of which is secured on the sleeve 336. It has been stated above that the sleeve 336 effects one revolution at each of the six multiplying operations. It results from the above that the shaft 415 will be rotated counter-clockwise when the bevelled pinion 421 is coupled with the pinion 423 and clock-

wise when the bevelled pinion 422 is coupled with the pinion 423. The multiplication tables 272 secured to the shaft 415 are therefore rotated accordingly.

5 *Sequence of operation of units multiplication tables*

The actuation of both shafts 355 and 415 and of the multiplication tables 271 and 272 for the units digit of the partial products, when the bevelled pinions 385 or 386 and 421 or 422 are engaged with their driving pinions 387 or 423 respectively (Fig. 71A), takes place in each of the six multiplying operations in the following sequence: First, one rotation of the shaft 355 in either direction, then either another rotation of said shaft in the same direction in which it was driven in the first rotation, or one rotation of the shaft 415 in either direction.

20 After these rotations, the shaft 360 and the cylinder 358 complete their rotation, whereby the inclined edges of the grooves 357 and 417 carry the studs 356 and 416 back into their middle positions; that is, if said studs were previously shifted (Figs. 30A, 30B, 33, and 57). Therefore, at the end of each multiplying operation, the arms 353 and 413 are returned to their initial positions, as also are the sleeves 354 and 414 and the bevelled pinions 385 and 386 and 421 and 422, as shown in Figs. 30A and 30B. In the same manner, the arm 392 and the sleeve 391, supporting the gear 401, are carried again to their initial positions by an inclined edge 437 of a drum 438 (Figs. 30A, 30B, and 34) in cooperation with a stud 436 on an extension of the arm 392, in case said arm was previously shifted out of its initial position by the cylinder 330. The drum 438 is fast on a shaft 440, the left end of which has secured thereto a gear 362 meshing with the intermittent driving mechanism including gears 363, 364, and 365 already explained (Figs. 12C and 57).

Return of the control cylinder to normal position

45 Referring to Figs. 12B, 12C, 32, and 57, in each multiplying operation the cylinder 330, after shifting laterally, is rotatively returned to its initial angular position and is therefore ready to be positioned according to the next multiplier 50 digit in the next multiplying operation. The angular restoration of the cylinder 330 is effected by a resetting mechanism comprising a gear 441 fast on the shaft 325. The gear 441 is connected by the gearing 326, 327, and 328 to said cylinder 330. The gear 441 meshes with a gear 442 connected by a sleeve 1442, free on the shaft 320, to a gear 443 which cooperates with a resetting gear 444 fast on a shaft 1444 journaled in the frames 1214 and 1217. Also fast on the shaft 1444 is a gear 445 connected by a gear 446 to an intermittent driving mechanism including gears 447 and 448, the driving gear 448 of which is secured to the sleeve 336 which, as stated above, makes one revolution in each of the six multiplying operations to angularly restore the cylinder 330.

55 It will be seen from the above (and from Figs. 71A and 71B) that the six multiplier storage wheels 301₁₋₆, after having been positioned simultaneously to the value of the six multiplier digits set up on the amount keys, are successively reset to zero and that the shaft 350 carrying the multiplication tables 273 for the tens values of the partial products, as well as the cylinder 330, are positioned to the corresponding value of said dig-

its (Figs. 17A, 17B, and 31). If the cylinder 330 is, for instance, rotated angularly in proportion to one of the multiplier digits, one or two or none of the three sets of projections 351, 394, or 411 may be carried opposite their respective studs 352, 393, or 412, so that the lateral shifting movement of said cylinder 330 will cause the corresponding arms 353, 392, or 413, together with the bevelled pinions 385, 386 and 421, 422 and the gear 401 to be shifted one way or the other or not at all (Figs. 30A and 30B). Therefore, either or both or neither, as the case may be, of the shafts 355 and 415 are connected with their driving gears 407 and 432 and are actuated in accordance with the multiplier digit considered at the moment.

Movement of units multiplication tables for different multiplier digits

The projections of the cylinder 330 are located in such a manner, with relation to their respective studs, that the coupling of the shafts 355 and 415 with their driving means, through the lateral shift of the said cylinder, gives the following kinds of drives for the different multiplier digits.

For the multiplier digit "0" (Figs. 30A, 30B, and 31), the shaft 355 and the shaft 415 receive no rotation at all. For the digit "1," the shaft 355 is rotated once in the clockwise direction, and the shaft 415 is not rotated. For the multiplier digit "2," the shaft 355 receives two clockwise rotations, and the shaft 415 is not rotated. For the digit "3," the shaft 415 receives one clockwise rotation and the shaft 355 one counterclockwise rotation. For the digit "4," the shaft 415 is rotated once in clockwise direction. For the digit "5," both shafts 355 and 415 rotate once in clockwise direction. For the digit "6," the shaft 415 rotates once in counter-clockwise direction. For the digit "7," the shaft 415 rotates once in counter-clockwise direction and the shaft 355 once in clockwise direction. For the digit "8," the shaft 355 rotates two rotations in counter-clockwise direction, and for the digit "9," the shaft 355 rotates once in counter-clockwise direction, the shaft 415 remaining stationary for these two digits.

In the following table, the number of revolutions of the shafts 355 and 415 are given for the different multiplier digits "0" to "9," the direction of rotation being indicated by the plus sign for the clockwise direction and by the minus sign for the counter-clockwise direction.

Multiplier digits	Shaft 355	Shaft 415
"0"	0	0
"1"	+1	0
"2"	+2	0
"3"	-1	+1
"4"	0	+1
"5"	+1	+1
"6"	0	-1
"7"	+1	-1
"8"	-2	0
"9"	-1	0

After the rotation of the shafts 355 and 415, those sleeves 354, 391, and 414, which were previously shifted, are restored to their initial positions, as shown in Figs. 30A and 30B, by the restoring cylinders 358 and 438. The cylinder 330 is also restored after the shafts 355 and 415 have been rotated. All the parts are again in their home positions and are positioned, during the next multiplying operation, according to the next higher order multiplier digit, the shafts 355 and

415 receiving the corresponding rotations as above described.

Units values of partial products

5 The multiplication tables 271 (Fig. 18) are mounted on the shaft 355 and the multiplication tables 272 on the shaft 415. Their rotation causes selected variable numbers of teeth of the tables to cooperate with the pinions 268 to provide the 10 units values of the partial products, as will now be explained.

The shaft 355 supports eight multiplication tables or bodies 271 (Figs. 12C and 18) corresponding to the number of denominations of multiplicand digits. These tables each comprise nine differential wheels 271₁₋₉, the left-hand or first wheel 271₁ having one tooth (Figs. 2 and 4), the second wheel, 271₂, two teeth, the third wheel, 271₃, three teeth, etc., wheel 271₉ having nine teeth. The shaft 415 supports, in the same manner, eight multiplication tables or bodies 272 (Figs. 18 and 22), each comprising nine differential wheels 272₁₋₉, the wheels in each group having respectively, beginning with the left-hand wheel, four, eight, two, six, nought, four, eight, two, and six teeth (Figs. 2 and 5). The multiplication tables 271 and 272 of each corresponding order cooperate with their respective gears 268 (Figs. 12C, 18, and 22), these gears being positionable in proportion to the multiplicand digits 1 to 9, as explained before, to select the suitable differential wheels 271₁₋₉ and 272₁₋₉. Resilient retaining pawls 269 hold the wheels 268 against unintentional rotation.

55 Rotation of the shafts 355 and 415, as required by the value of the multiplier digit, causes the selected wheels of the tables 271 and 272 to rotate the corresponding wheels 268 with respect to the number of teeth of the selected wheels of the multiplication tables 271 and 272 and also with respect to the number of rotations of the multiplication tables and their direction of rotation as controlled by the mechanism in Figs. 30A and 30B and described earlier herein.

45 Each of the shiftable gears 268 (Figs. 12A and 12B) is arranged to cooperate with a wide gear 451 having ten teeth, and these gears form what will be known as "the units partial product storage device." Each gear 451 is held against unintentional rotation by a resilient ratchet pawl 452 (Figs. 18 and 22). Each of the wheels 268, after its shifting movement corresponding to the multiplicand digit, is rotated, as explained above, a given number of divisions in one or the other 55 direction in each of the six multiplying operations. Such rotation of the gears 268 is transmitted to the corresponding units partial product storage gears 451 (Figs. 71A and 71B) with which they have been engaged in the meantime. The 60 gears 451 are therefore positioned, at each multiplying operation, proportionate to the value of the units values of the partial product considered.

All the storage gears 451 are loosely mounted 65 on a shaft 450 supported by two arms 453 of a yoke 454 mounted on the shaft 250 (Figs. 12A, 12B, 18, and 22). The right-hand arm of the yoke 454 is connected by a sleeve 455 to a cam lever 456 (Fig. 49) carrying the rollers 457 and 70 458 which cooperate respectively with companion plate cams 461 and 462 free on the shaft 214. The plate cams are connected, by gears 463 and 464, to an intermittent driving mechanism including gears 465 and 466, the driving gear 466 75 of which is secured to the shaft 210. Owing to

the gears used in this intermittent driving mechanism and to the form of the cams 461 and 462, the shaft 450 and the units partial product storage gears 451 are rocked (Figs. 71A and 71B) during each of the six multiplying operations to disengage the storage gears 451 from the pinions 268 and to engage a gear 467, integral with each of the storage wheels 451, with an intermediate gear 468 loosely mounted on a shaft 470 journaled in the frames 1214, 1215, and 1216 (Figs. 12A, 12B, 12C, 18, and 22). Each of the gears 468 meshes with one of the ring gears 234 and is locked against unintentional rotation by means of a resilient ratchet pawl 469 (Fig. 18). The pawls 469, which, as described below, also serve to prevent any acceleration of the ring gears 234 during the tens transfer, are disengaged from the gears 468 during the transfer of the units values of the partial products.

A gear 471 is secured on the side of each storage wheel 451 and, together with a toothed locking disc 472, secured to the shaft 470, constitutes a resetting mechanism. Secured on the right end of the reset shaft 470 is a gear 473 (Figs. 12C and 59), which is connected by an intermediate wheel 474 with an intermittent driving mechanism including gears 475 and 476, the driving gear 476 of which is secured to the sleeve 336. As the gear 476 effects one revolution at each of the six multiplying operations, the reset shaft 470 is rotated once at each of these six operations and at the moment when the units partial product storage gears 451 are engaged with the gears 468, and the resetting gears 471 and 472 are engaged with each other. The rotation of the reset shaft 470 causes the units partial product storage gears 451, previously positioned to the units values of the computed partial product, to be reset to zero and the values thereon transmitted to the corresponding ring gears 234 and 222.

After this transfer, the units partial product storage gears 451 are disengaged from the reset storage wheels 472 and carried in mesh with the corresponding pinions 268, so that the units partial product values of the next higher order multiplier digit may be formed. In this manner, all the units of partial products are obtained for the eight denominational orders of the multiplicand by the successive multiplication thereof by the six multiplier digits, and these partial products are transferred to the ring gears 234 and 222.

Tens values of partial products

As above stated, the positioning of the control cylinder 330 (Figs. 30A and 30B) to the value of the multiplier digit introduced at the moment, causes the rotation of the shaft 350 and the eight multiplication bodies 273 for the tens partial product values (Figs. 11C and 23) to an angle corresponding to said digit (Figs. 71A and 71B). Each of the multiplication bodies 273 comprises eight differential wheels 273₂₋₉ (Fig. 23), and these wheels are provided with teeth conforming in number and arrangement to the table (Fig. 8).

In each denominational row, the pinion 264 is shifted to the left, or upwardly, in proportion to the multiplicand digits entered in the various orders and is therefore positioned opposite the corresponding differential wheels 273₂₋₉. When the shaft 350 and the multiplication tables or bodies 273 rotate in proportion to the multiplier digit, the active wheels 273₂₋₉ produce a corresponding rotation of the pinions 264. Each of the pinions 264 is permanently in mesh with a corresponding wide gear 481 (Figs. 11C and 23)

loosely mounted on a shaft 480 and integral with a gear 482. The gears 482 are each in mesh with a corresponding one of the seven ring gears 234 of the denominational orders 2 to 8 and with the ring gear 234a of the ninth order.

It has been stated that the ring gears 234 and 234a are operatively connected to the corresponding ring gears 222 and 222a. The rotation given to the pinions 264 by the selected differential wheels 273₂₋₉, when a multiplier digit is introduced, is therefore transmitted, as the tens values of the partial product, to the corresponding tens gears 481 and then through the gears 482 to the ring gears 234 and 222.

Product accumulator

At each of the six multiplying operations, the units values of the partial products, computed in the eight orders, are transmitted to the corresponding eight ring gears 222 of the first to eighth denominational orders, and the tens values of these partial products are transmitted to the seven ring gears 222 of the second to eighth rows and to the ring 222a of the ninth, or overflow, row (Figs. 11A, 11B, 12A, 12B, 22, 23, and 29). Besides the nine ring gears 222 and 222a, the multiplying unit further comprises five ring gears 222b and 222c for the product capacity.

Actuators for the product accumulator

Each of these fourteen ring gears 222, 222a, 222b, and 222c is in mesh with a corresponding actuator gear 501 (Figs. 10A, 10B, 11B, 35, 40, and 43), each of which gears is pivoted on a stud 502 in a slide 503. All the slides 503, except that of the lowest order, are shiftably mounted on two fixed studs 504, and each slide carries a stud 505 upon which pivots a locking lever 506 urged clockwise by the action of a spring 507, to normally maintain an extension thereof hooked under a cross bar 508. The hooked part of the lever 506 thus determines the extent of displacement of the slide 503, which movement takes place under the action of its spring 509 (Fig. 35). The actuator gears 501 are in the plane of a series of adding wheels 511, each having twenty teeth, and these adding wheels constitute a fourteen-order product accumulator in which the units and tens amount of various partial products are accumulated to form a complete product.

Transfer and denominational shift in general

Each adding wheel 511 is integral with a tens transfer disc 512 having two transfer teeth which cooperate with a nose 513 provided on the locking lever 506 of the next higher order. All adding wheels 511 and their tens transfer discs 512 are rotatably but unshiftably mounted on a sleeve 515 free on the shaft 510. The sleeve 515 is supported by two arms 516 which are themselves free on a shaft 520 and are connected to each other by a sleeve 517. The arms 516 and the sleeves 515 and 517 form a shiftable frame for the product accumulator, and this frame is connected to a shifting arm 518 guided by a shaft 521 and said arm shifts laterally with the frame but does not participate in the rocking movement thereof. The arm 518 has a roller 522 which cooperates with a groove in a shifting drum 523 loose on a shaft 525 (Figs. 10A, 10B, 11B, 11C, 35, and 40). A driving mechanism, later to be described, rotates the drum 523 one-tenth of a

revolution during each of the six multiplying operations and, due to the form of the groove therein (Fig. 37), said drum shifts the product accumulator from its initial position, as shown in Fig. 40, one denominational row toward the right each multiplying operation (see also Figs. 29, 71A, and 71B). Therefore the nine ring gears 222 and 222a, which, as described above, are positioned according to the units and tens values of the partial products, are successively connected to the adding wheels 511 of the next higher denominational row in each multiplying operation.

Product accumulator engaging mechanism

To engage the adding wheels 511 with the suitable actuator gears 501, after each denominational shift, the shaft 510 is connected to one end of a link 531 (Figs. 11B, 35, and 40), the other end of which is connected to an arm 532 fast on a shaft 533. The shaft 533 fixedly supports a lever 534 (Figs. 11A, 11B, 51, 52, and 55) carrying the rollers 535 and 536 which cooperate alternately with one or the other of two pairs of companion plate cams 537, 538 and 539, 540 secured to a common hub 541 (see also Fig. 12A). The hub 541 is shiftably but not rotatably mounted on a sleeve 1541, free on the shaft 214, and has integral therewith a gear 551. An annular groove in the hub 541 is embraced by an arm 542 shiftably mounted on the shaft 220 and said arm carries a roller 543 which engages a groove in a drum 544. The drum 544 is loosely mounted on the shaft 210 and is connected by a gear 545, integral therewith, and a gear 546 to an intermittent driving mechanism comprising gears 547 and 548, the driving gear 548 of which is fast to the main shaft 210.

The above intermittent driving mechanism effects one-half a revolution of the grooved drum 544 at the beginning and again at the end of the six multiplying operations, and this causes, in view of the shape of the groove (Fig. 38) the two pairs of cams to be shifted so as to position the cams 537 and 538 in the path of the lever 534 during the six multiplying operations, whereas the cams 539 and 540 are positioned in the path of said lever after the end of the six multiplying operations.

The sleeve 1541 is connected, by the gear 551 and a gear 552, to an intermittent driving mechanism comprising gears 553 and 554 (Fig. 12A), the driving gear 554 of which is fast to the shaft 210. By means of this mechanism, each of the pairs of cams rotates one-half a revolution during each of the six multiplying operations and a further one-half revolution during a total or product printing operation which immediately follows, as will be described later.

The cams 537 and 538, which are active during the six multiplying operations, are shaped (Fig. 51) so as to cause two rocking movements of the lever 534 at each of said six multiplying operations. These movements are transmitted, by the shaft 533, the lever 532, and the link 531 (Figs. 10A, 10B, and 35), to the accumulator frame arms 516, in such a manner that the adding wheels 511 are engaged with and disengaged from the gears 501 twice during each of the six multiplying operations (Figs. 71A and 71B); that is, connected with the ring gears 222 and 222a, a first time for the transfer of the tens values and a second time for the transfer of the units values of the partial products to the product accumulator.

Denominational shift of the product accumulator

It has already been mentioned that the product accumulator remains in the home position during the first multiplying operation and that the nine first adding wheels 511 are thus in the plane of the actuator gears 501 and their corresponding nine ring gears 222 and 222a of the nine first orders, as shown in Fig. 40. As stated above, the adding wheels 511 are engaged with the ring gears 222 and 222a first during the transfer of the tens values of the first partial product and then, after a short period of disengagement, are engaged again during the transfer of the units values of said first partial product. Before computing and transmitting the tens and units values of each further partial product, the product accumulator is shifted one order or denominational row to the right (Figs. 40, 71A, and 71B) by the one-tenth revolution of the grooved drum 523 (Figs. 11B and 11C). The drum 523 is connected by a sleeve 561, free on the shaft 525, to a gear 562 (Figs. 11C, 12C, and 56) connected by a gear 563 to a pinion 564 secured on the shaft 220.

Another pinion 565 (Fig. 12B) secured on shaft 220 may be coupled with either of two pinions 566 and 567 free on the shaft 220 by a coupling device now to be described.

The coupling pinions 568 and 569 (Figs. 12B, 41, and 42) are mounted on a lever 571 pivoted on the shaft 533. The lever 571 carries rollers 572 and 573 which cooperate respectively with companion plate cams 574 and 575 fast on the driving shaft 210 (see also Fig. 54). The lever 571 is rocked, by the plate cams, to engage either of the pinions 566 or 567 with the pinion 565. The contour of the cams 574 and 575 is such that the lever 571 rocks first clockwise, before the beginning of the six multiplying operations, to cause the coupling pinion 569 to couple the pinions 567 and 565. After the multiplying operations are completed, the cams 574 and 575 return the lever 571 to its initial position, as shown in Fig. 41, to disengage the pinion 569 and to reengage the pinion 568 with the gears 565 and 566. The coupling pinion 568 or 569 which is in the disengaged position is held stationary by a locking member 576.

The gear 567 (Fig. 12B) is connected, by a gearing 578 to 581, to an intermittent driving mechanism comprising gears 582 and 583, the driving gear 583 of which is secured to the main shaft 210. In view of this arrangement, the gear 578, free on the shaft 210, is rotated one-half of a revolution in the counter-clockwise direction at each of the six multiplying operations. This wheel 578 communicates its movement to the gear 565, connected thereto at the moment, at each multiplying operation, and this partial rotation is transmitted, by the shaft 220 and the gears 564, 563, and 562, to the grooved drum 523 which rotates one-tenth of a revolution each multiplying operation. The shape of the groove causes the product accumulator, as aforesaid, to be shifted one denominational order at each partial operation. There are five such shifts in all, so that the units and tens partial product values, obtained during these operations, are transmitted from the ring gears 222 and 222a to the adding wheels 511 of the next higher order.

Transfer mechanism

If, during this transmission, one of the adding wheels 511 passes from "9" to "0," the transfer

tooth of the corresponding transfer disc 512 (Figs. 35 and 40) contacts the nose 513 of the lever 506, which, as aforesaid, is connected to the slide 503 of the next higher order. The lever 506 is therefore moved counter-clockwise, against the action of the spring 507, to remove the lower hook thereof from the cross bar 508, thereby leaving the spring 509 free to pull the slide 503 upwardly. Upward movement of the slide 503 causes the intermediate gear 501 to roll on the outside teeth of the ring gear 222, which is stationary at this moment, to communicate a rotation of one unit to the adding wheel 511 of the next higher order.

Transfer restoring mechanism

After each transfer of the units as well as of the tens values of the partial products in each of the six multiplying operations, the tens transfer parts which have been tripped have to be restored to their initial position. A transfer restoring cross bar 587 (Figs. 12B, 12C, and 35) is supported by two arms 588 integral with a sleeve 589 free on the shaft 470. The cross bar 587 cooperates with shoulders 586 of the slides 503. The sleeve 589 (Fig. 50) is rigidly connected to a lever 591 carrying rollers 592 and 593 which cooperate respectively with companion plate cams 594, 595 secured on the shaft 214. The plate cams are connected, by gears 596 and 597 (Fig. 12B), to intermittent driving mechanism comprising gears 598 and 599, the driving gear 599 of which is fast to the shaft 210. The gear 599 has a toothed portion located in relation to the gear 598 so that the cams 594 and 595 effect three revolutions at each of the six multiplying operations. In view of the shape of the cams 594 and 595, the lever 591 and the cross bar 587 (Fig. 35) oscillate twice during each partial operation (Figs. 71A and 71B), once after the transfer of the tens values and once after the transfer of the units values of each partial product.

The restoring movement of the cross bar 587 returns the previously tripped slides 503 downwardly until the hooks of the levers 506 reengage the cross bar 508, thus maintaining the tens transfer parts in the untripped position until the next multiplying operation. The restoring bar 587 is then returned to its initial position by the cams 594 and 595.

Resetting of the product accumulator

When all units and tens values of the six partial products have been successively transmitted to the product accumulator, a printing operation by the accounting machine is automatically performed to print the complete product and, if desired, transfer said product to the accumulators of the accounting machine. Before doing this, however, the product accumulator must be shifted back to a position where the decimal point of the wheels 511 will coincide with that of the accounting machine actuators and printing segments.

In the present embodiment of the invention, it is assumed that the multiplicand and multiplier have no more than two decimal orders after the decimal point. Therefore, the complete product will have a maximum of four decimal orders and for this reason the product accumulator is arranged to take care of four decimal orders, which arrangement also includes reset devices and tens transfer devices for these orders. In Figs. 26 and 29 these decimal orders are identified by the index "d."

Prior to being reset, the product accumulator is returned laterally three orders to the left (Figs. 29, 40 and 71B) to align the denominational orders thereof with the ring gears 222 which are connected to the corresponding orders of the accounting machine actuating and printing mechanism, preparatory to transferring the complete product to said accounting machine mechanism. This is effected by movement of the cams 574 and 575 (Figs. 12B, 41, 42, and 54) which rock the lever 571 clockwise, near the end of the six multiplying operations, to disengage the pinion 569 and to engage the pinion 568. The pinion 566 is connected by the gears 601 to 604 inclusive, to an intermittent driving mechanism including gears 605 and 606, the driving gear 606 of which is fast to the shaft 210.

Near the end of the sixth multiplying operation, the driving gear 606 causes the pair of gears 605 and 604 to rotate two-thirds of a revolution, which movement is transformed, by the gears 603 and 602, into a complete revolution of the driving gear 601. The driving gear 601 has two toothed portions which rotate the gear 566 one partial rotation before and one partial rotation after the resetting of the product accumulator.

As the gear 566 is now coupled to the gear 565, the two partial revolutions thereof are transmitted, by the shaft 220 and the gears 564, 563, and 562 (Figs. 11B, 11C, 12B, and 12C), to the grooved drum 523, which therefore effects two one-tenth revolutions before and two one-tenth revolutions after the resetting of the product accumulator, and thus said accumulator is returned to its initial position.

The groove in the drum 523 is so shaped (Fig. 37) that the first of its two partial rotations shifts the product accumulator three rows to the left or upwardly (Figs. 29, 40, and 71B) before the resetting operation to position the adding wheels 511 of said accumulator in proper denominational relationship with the actuator ring gears 222, 222a, 222b, and 222d.

At this time, the setting segments 208, 208a, 208b, and 208d (Figs. 17A and 17B), which provide a connection between the multiplying mechanism and the accounting machine, are again engaged (Fig. 71B) with the ring gears 222, 222a, 222b, and 222d. This engaging of the segments 208 is effected by means of one of the sets of differential teeth on the driving gear 221 (Fig. 12B) which rotates the cams 215 and 216 one-fourth of a revolution to rock the arms 211 (Figs. 10A, 10B, 17A, and 17B) and the shaft 209 counter-clockwise to engage said segments 208 with the corresponding ring gears 222.

The shaft 209 (Figs. 10A, 10B, 11B, 17A, and 17B) has secured thereon a lever 611 adjacent each of the setting segments 208, and a bent-over portion 613 of these levers contacts, under the action of their springs 612, a shoulder 614 of a common locking yoke 615 loosely mounted on the shaft 210. The left-hand arm of the yoke 615 has a Y-shaped extension 616 carrying rollers 617 and 618 (Figs. 12B and 53) which cooperate respectively with plate cams 619 and 620 mounted on the shaft 214. The cams 619 and 620 are connected by gears 621 and 622 to an intermittent driving mechanism including gears 623 and 624, the driving gear 624 of which is fast on the shaft 210. The gear 624 causes the gears 623 and 622 to rotate two-thirds of a revolution during the sixth multiplying operation, which movement is transmitted through the gears 622 and 621 (Fig. 11B) to the cams 619 and 620 to rotate them one

revolution. Rotation of the cams 619 and 620 rocks the yoke 615 clockwise, just before the resetting movement of the product accumulator and in the contrary direction near the end of the resetting operation. The rocking movement of the yoke 615 in the clockwise direction (Figs. 17A and 17B) causes the shoulders 614 to be removed from the bends 613 so that the levers 611 may contact, with their second bent parts 625, the arms of the setting segments 208, under the 10 action of their springs 612.

Simultaneously, the grooved drum 544 shifts the cams 539 and 540 (Figs. 11A, 12A, 51, and 52) into cooperative relationship with the rollers 535 and 536, and operation of said cams, through the shaft 533 and the linkage 532 and 531 (Fig. 35) rocks the wheels 511 of the product accumulator into engagement with the intermediate gears 501 (Fig. 71B) to connect said wheels 511 to their corresponding ring gears 222, 222a, 222b, and 222d.

During this last cycle of operation, the accounting machine is clutched, as described before, with the machine drive and effects a complete operation. The zero stop pawls for the racks 204 (Figs. 10A and 10B) are tripped, as usual in total taking operations, and said racks follow the leading frame 632 during its initial movement counter-clockwise, to cause the levers 206 and the links 207 to actuate the setting segments 208 accordingly (Fig. 71B). The yoke 614 (Figs. 17A, 17B, and 71B), being removed from the ears 613, permits the springs 612 to urge the levers 611 counter-clockwise to assist the segments 208 in turning the wheels 511 of the product accumulator reversely. Reverse rotation of the wheels 511 (Fig. 35) is arrested when one of the two transfer teeth 512 contacts a nose 634 of a stop lever 635 to locate said wheels in zero position and to transfer the product to the accounting machine actuators and by them to the printing mechanism and, if desired, to one or more of the accounting machine accumulators.

The lever 635 are loose on a shaft 636 of the product accumulator frame and are maintained by springs 637 in contact with a cross rod 638. The shape of the noses 634 permits the transfer teeth to by-pass them when the wheels 511 are turned in a counter-clockwise or positive direction.

Each of the wheels 511 is therefore reversely rotated a distance correspond to the value previously accumulated thereon, and the gear 501, ring gear 222, segment 208, and link 207 (Figs. 10A, 10B, 17A, 17B and 35) rock the reducer arm 206 counter-clockwise in proportion to said value to position the type segments 1211 so that the complete product may be printed.

During the resetting of the product accumulator, the two lowest order wheels 511 (the third and fourth orders after the decimal point) are connected, by two intermediate gears 501d, (Fig. 40) to the corresponding ring gears 222d, which in turn mesh with the setting segments 208d. However, it is unnecessary to provide racks 204 and corresponding type segments for the segments 222d, since only the two orders after the decimal point are printed in the complete product. For this reason, the two lowest orders do not comprise the usual tens transfer mechanism and therefore it is unnecessary for the intermediate gears 501 and 501d of the three lowest orders to shift with the gears 501 of the higher orders, and therefore they are mounted on a stud 502d in a fixed bracket 503d, as said gears

are used only for resetting the product accumulator.

Disengaging and restoring of the product accumulator

Shortly after the resetting operation, the cams 539 and 540 (Figs. 11A, 12A, 51, 52, and 71B) disengage the product accumulator from the intermediate gears 501.

After this, another toothed portion of the driving gear 601 (Fig. 12B) becomes active and, through the gearing 566, 568, and 565, shaft 220, and gears 564, 563, and 562, rotates the grooved drum 523 the remaining two-tenths of a revolution until it is again in its initial position. The contour of the groove in the drum 523 (Fig. 37) shifts the product accumulator two orders to the left to its home position (see also Fig. 29).

20 The leading frame 632 of the accounting machine (Figs. 10A, 10B, 17A, and 17B) is then restored clockwise and the setting racks 204 are positively returned thereby to zero position. Through the medium of the levers 206 and the 25 links 207, the setting segments 208 are also returned to home position (Fig. 71B). The transverse rod 228 assists in this restoring movement of the segments 208, as it is moved clockwise at this time by the cam 227.

Restoring of the multiplicand mechanism

Teeth on a gear wheel 701 (Figs. 11C, 12C, and 56), secured to the shaft 210, engage and rotate, at this time, a gear 702 connected by gears 703, 35 704, and 705 to a gear 706 fast to the shaft 525. A grooved drum 708 (Fig. 11B), also secured to the shaft 525, is therefore rotated one revolution during the last multiplying operation. The groove in the drum 708 cooperates with a roller 40 709 (Fig. 21) supported by a toothed rack 710 which slides horizontally on two studs 711. The rack 710 meshes with eight pinions 712 loosely mounted on the shafts 239 and each pinion 712 has integral therewith a restoring arm 713 (Figs. 45 11A, 11B, 19, and 20). The arms 713 are each in the plane of a bent-over ear of a series of 50 stop levers 715 secured to each of the locking shafts 240 fast on the shafts 239. When the multiplicand is set up, each of the 55 shafts 239 (Fig. 20) and their corresponding stop levers 715 are positioned clockwise proportionate to the digits of the multiplicand to bring the edges of the ears of the arms 713 nearer the edges of the stop levers 715.

During the sixth multiplying operation, the 60 rotation of the grooved drum 708 (Fig. 39) shifts the rack 710 (Fig. 21) to rotate the wheels 712 and arms 713 counter-clockwise (Fig. 20). Counter-clockwise movement of the arms 713 return the levers 715 from their moved or at positions to zero position and this movement is transmitted by the toothed part of the shafts 239 to the racks 261 and 265 to return the pinions 65 264 and 268 to home position (see also Figs. 18 and 71B).

Simultaneously the locking yoke 615 (Figs. 17A and 17B) is restored to home position, as here shown, by the cams 619 and 620 and the intermittent driving mechanism including gears 624 and 623 to return the shoulders 614 beneath the bends 613 of the levers 611, to hold said levers against the action of the springs 612. All parts of the machine are thus restored to their initial or home positions and the machine is now ready 75 for another problem of multiplication.

Machine operation

Even though it involves considerable repetition, it is believed that an outline of the mode of operation of the machine of this invention will assist in recalling to mind the many novel features of said machine.

It will be recalled that a complete performance of a problem of multiplication consists of nine operations—one for entering the multiplicand, one for entering the multiplier, six for multiplying the multiplicand by each of the six, or less, digits of the multiplier, and one for resetting the product accumulator and registering and recording the complete product.

To enter the multiplicand, the operator depresses the suitable amount keys 201 (Figs. 10A and 10B) and then the multiplication key 202 to clutch the accounting machine and the multiplying mechanism with the main driving gear 652 (Figs. 13 and 14). Then the machine operation is initiated by depressing the motor bar 203.

The actuator racks 204 are positioned commensurate with the depressed amount keys and the positions thereof are transmitted to the setting segments 208. Then the segments 208 are carried into mesh with the corresponding ring gears 222 and simultaneously the bevelled pinions 238 engage the pinions 237 (Figs. 18 and 19). The racks 204 and the setting segments 208 are then restored to zero position to cause the pinions 268 and 264 (Figs. 22 and 23) of each order to be positioned in relation to the multiplication tables 271, 272, and 273 and in proportion to the value of the multiplicand digits.

After this, the bevelled pinions 238 are disengaged from the pinions 237 and the setting segments 208 from the ring gears 222. The first operation is completed and the machine comes to rest in home position.

The multiplier is then set up on the amount keys 201 and the multiplication key 202 is again depressed. The depression of the motor bar 203 releases the machine for eight automatic sequential operations, and in the first of these eight operations the racks 204 and the setting segments 208 (Figs. 10A, 10B, 11B, 17A, and 17B) are positioned commensurate with the value of the multiplier digits. After this positioning, the setting segments 208 and the multiplier storage wheels 301₁₋₆ are carried into mesh with the ring gears 222 (Fig. 12B). During the restoring movement of the segments 208, the storage wheels 301₁₋₆ are positioned according to the multiplier digits. Then the setting segments 208 and the multiplier storage wheels 301₁₋₆ are disengaged from the ring gears 222. The accounting machine has now completed its second operation and remains at rest in the home position, the groove 660a causing the driving mechanism thereof to be disconnected from the main driving wheel 652 (Figs. 13 to 16). However, the main shaft 210 continues to operate and causes the multiplying mechanism to operate automatically during the remainder of the performance of the multiplication.

In the six multiplying operations, which follow without interruption, the multiplicand is successively multiplied by each of the six multiplier digits and the units and tens values of the partial products thus obtained are computed separately and successively transmitted to the product accumulator. During the first of the six multiplying operations, the first storage wheel 301₁ is connected to the corresponding resetting wheels 318, 319, and 321, 322 and with the cor-

responding gear 316 (Figs. 11A, 11B, 12B, 17A, and 17B). By the resetting of the storage wheel 301₁, the value of the multiplier digit thereon is transmitted, through the gears 316, 317, 326, 327, and 328, to the control cylinder 330 and then through the gears 345 to 348 to the shaft 350 supporting the multiplication tables or bodies 273 for the tens partial product values.

The product accumulator is in its initial position, as shown in Fig. 40, in which the adding wheels 511 are in alignment with the ring gears 222 of the corresponding orders. The storage wheel 301₁ is now disengaged from the resetting mechanism and simultaneously the cylinder 330 receives its axial back and forth movement (Figs. 30A, 30B, and 31). According to the position of the cylinder, proportionate to the multiplier digit, the operation of the shafts 355 and 415 is determined.

After the product accumulator has been engaged with the ring gears 222 (Fig. 35), the cylinder 330 is restored radially to its home position. Simultaneously the shaft 350, supporting the multiplication bodies 273 for the tens values of the partial products, is revolved a number of divisions or steps corresponding to said multiplier digit (Figs. 11A, 11B, 12A, 12B, 17A, and 17B). By this movement, the differential teeth of the selected multiplication wheels 273₂₋₉, through the pinion 264, cause the rotation of the gears 481 and 482, and these gears, through ring gears 234 and 222, rotate the wheels 511 of the product accumulator a corresponding angle to transfer the tens values of the first partial product thereto.

If, during this registration, any of the tens transfer or carrying devices are tripped (Fig. 35), they are restored to untripped positions against the action of their springs 509 by the downward movement of the bar 587.

At the same time, the shafts 355 and 415 are rotated by their operating mechanism (Figs. 30A and 30B), the extent and direction of the rotation of the shafts being controlled by the cylinder 330, and cause the selected wheels 271₁₋₉ and 272₁₋₉ of the multiplication tables to rotate the pinions 268 in proportion to the units digits of the various partial products. At this time, the units partial product storage gears 451 of the various orders are engaged with the pinions 268 (Figs. 18 and 22) and receive, therefore, the units values of the first partial product. The units partial product storage gears 451 are then engaged with the reset gears 472 and reset to zero. During this resetting, the units values obtained in each order are transmitted by the ring gears 234 and 222 to the corresponding wheels 511 of the product accumulator.

If a tens transfer occurs, when one of the wheels 511 passes from "9" to "0," the transfer tooth of the disc 512 thereof rocks the locking lever 506 in such a way that the spring 509 pulls the intermediate slide 503 upwardly, which causes the intermediate gear 501 to roll on the outside teeth of the stationary ring gear 234, thus adding one unit in the next higher order.

After the registration of the tens and units amounts of these first partial products and after the tens transfer, the product accumulator is again disengaged and the rotation of the drum 523 shifts said product accumulator one order to the right (Figs. 17A, 17B, and 40). Simultaneously, the multiplier storage wheel 301₂ of the second order is coupled to the corresponding reset gears 321 and 322 and the multiplicand is

multiplied, by the second digit of the multiplier, in the same manner as explained above for the first digit. The units and tens values of the second partial products are transmitted to the product accumulator in the same way as those of the first partial products.

The remaining partial products are formed under control of the third, fourth, fifth, and sixth multiplier digits and are transmitted to the product accumulator, which is shifted, as multiplication progresses, order by order toward the right. In this manner all units and tens values of the six partial products are, in accordance with their denominational order, accumulated additively in the product accumulator, which now contains the complete product.

In the last or ninth operation, the accounting machine is again clutched to the main driving mechanism and the complete product is cleared out of the product accumulator and printed. To accomplish this, the product accumulator is first shifted back, or toward the left, three orders by the drum 523 in order to bring the adding wheels 511 of the various denominational orders as units, tens, hundreds, etc., opposite the ring gears 222 which control the actuation of the corresponding orders of the accounting machine (Fig. 29). Then the product accumulator (Fig. 35) and the setting segments 208 are engaged with the ring gears 222 (Figs. 17A and 17B).

Under the action of the springs 612, the setting segments 208 are rocked counter-clockwise (Figs. 10A, 10B, and 11B) and, through the ring gears 222 and the intermediate gears 501, the adding wheels 511 are reset and the value of the complete product, cleared therefrom, is transferred to the printing segments 1211 of the accounting machine to print the complete product.

Modified form

Figs. 60 to 70 inclusive illustrate a modified form of mechanism in which the two sets of multiplication bodies or tables, for computing the units values of the partial products, are much less complicated, in construction and operation, than the corresponding tables of the preferred form.

The nine digits 1 to 9 may be considered as the combination of two figures, these two figures being selected in such a way that their combination constitutes said digits 1 to 9. The pairs of figures 1 and 4 or 2 and 3 are suitable for this purpose and each of these figures may also be replaced by its complement.

In using the pair of figures 1 and 4, one may obtain the units values of all partial products by combinations of these figures as illustrated in Fig. 60. This means that in each order, only two differential wheels are necessary, one of said wheels having one tooth and the other having four teeth. The manner of selecting and controlling these two wheels is to be effected according to the table of Fig. 60. This table shows that the fifth vertical row and the fifth horizontal row are axes of symmetry with regard to the four rectangles of the table, as the values of the left upper rectangle are reflected images of the three other rectangles, the signs + or - being the same in the upper left and in the lower right rectangles, whereas they are reversed in the two remaining rectangles.

The tables of Figs. 61, 62, and 63 show separately the different combinations of the values "1" or "4" in the left upper rectangle of the ta-

ble of Fig. 60, Fig. 63 showing the position of the double "1" values.

As in the previous mode of operation, the control of the multiplication tables is effected by the projections on a control cylinder 1035, the development of which is illustrated in Fig. 65. This cylinder comprises groups of projections corresponding to the values +1, -1, +4, -4, and double "1" or 1+1 of the left upper rectangle of the table. The periphery of the cylinder 1035 is divided into six sections corresponding to the multiplicand figures 1 to 9. Each denominational order comprises one of the cylinders 1035, which is adapted to be positioned so that the section corresponding to the digit considered in its particular order, is effective.

When a multiplier digit is registered, the cylinders 1035 of all orders are rotated commonly within the selected multiplicand section an extent corresponding to the particular multiplier digit, it being understood that the sections provided for the multiplier digits 6 to 9 correspond to the sections provided for the multiplier digits 4 to 1.

By an axial back and forth movement of the cylinders 1035, the differential wheels 1021 and 1022, having one and four teeth respectively, may be brought in register with either of two gear sets 1065 and 1066 or 1067 (Figs. 64 and 66) which rotate in reverse directions. Therefore, the rotations of the differential wheels 1021 and 1022 (according to the signs given in the left upper rectangle of the table, Fig. 60) are transmitted in a positive or negative direction of rotation to a common intermediate wheel 1068.

The projections corresponding to the values double "1" or 1+1 furthermore cause a shifting movement of a sleeve bearing a pinion 1071 connected to the wheel 1021 (Fig. 66) so that the pinion 1071 may be meshed either with a driving wheel 1072, producing one revolution of the wheel 1021, or with a driving wheel 1073 producing two revolutions of said wheel 1021.

The actuation of the differential wheels 1021 and 1022 is controlled, in each order, in accordance with the table of Fig. 60, so that for the units values of the partial products obtained from any multiplicand digit 6 to 9 and from any multiplier digit 1 to 5 a reverse movement will take place with relation to the units values of the partial products obtained from the multiplicand digits 1 to 5 and the multiplier digits 1 to 5. Also, for the units values of the partial products obtained from the multiplier digits 6 to 9 and the multiplicand digits 1 to 9 another reversing of rotation is necessary with relation to the partial products obtained from the multiplier digits 1 to 5 and from the multiplicand digits 1 to 9. The first manner of reversing, which depends upon the multiplicand digits, must be effected separately in each order, whereas the second manner of reversing, which depends upon the multiplier digits, is effected in the same way for all the denominational orders. The above-described reversing of rotation may be effected by any suitable mechanism, and for this reason no such mechanism is illustrated or described herein.

The resetting operations for the transfer of the units values of each partial product are unnecessary if provision is made for a units storage device which continuously records the units values and which is shifted one decimal order for each partial product, in the same way as the product accumulator in the preferred form. This units storage device, at the end of the multiply-

ing operation, contains the sum of the units of all partial products, which are then transmitted to the product accumulator to obtain the complete product. The tens values are computed, in this case as in the preferred form, and are transferred directly to the product accumulator during each multiplying cycle.

The accumulation of the units values, which are represented partly by their positive effective values and partly by their negative complementary values, makes it necessary to effect certain tens corrections.

As an example, if one wheel of the units storage device is positioned to the value "3" and it is desired to add the value of the partial product $2 \times 4 = 8$, according to the table of Fig. 60, said wheel is not advanced eight divisions, but only $-1 - 1 = -2$; in other words, it will be positioned to the value $3 - 2 = +1$, while in reality the value $3 + 8 = 11$ should be transmitted.

As another example, if one of the storage wheels is positioned to the value "1" and it is desired to add the value $-1 - 1$, said wheel would have thereon, after the transfer.

$$+1 - 1 - 1 = -1$$

which is the corresponding complement to the desired position $1 + 8 = 9$.

For certain initial positions of the storage wheels, it is therefore necessary to omit a tens transfer. This error may be corrected by having an additional tens value provided in the tens value partial product wheels for all corresponding units values which control a back rotation of the storage wheels. This error may also be corrected by providing the units storage device with positive and negative tens transfers, whereby the negative tens are accumulated separately. Taking the above example, $3 + 8 = 11$, the tens transfer omitted in this case is effected by an additional tooth on the multiplication bodies for the tens partial product values. For the example $1 + 8 = 9$, the correct positioning of the value 9 leads to a negative tens transfer

$$(+1 - 1 - 1 = -1)$$

and this cancels the transfer produced by the additional differential tooth provided in the multiplication body for the tens.

If the above system of tens correction is applied to the example of Fig. 60, a combination is obtained as per Fig. 68 which gives the correction of the tens. It may be seen therefrom that a tens correction is necessary for each negative unit value of Fig. 60. In comparing the combination of the original tens values of Fig. 3 with the table of the tens corrections, Fig. 68, a resulting table may be deduced (Fig. 69), showing the number of differential teeth for the different tens values. The hatched parts thereof correspond to the position for which a differential movement is to be effected for the first time; in other words, Fig. 69 shows the positions in which the multiplication tables for the tens values must have a differential tooth. Fig. 70 shows a diagrammatic view of the arrangement of the differential teeth for the multiplication bodies corrected in this manner.

While the form of mechanism herein shown and described is admirably adapted to fulfill the objects primarily stated, it is to be understood that it is not intended to confine the invention to the one form or embodiment herein disclosed, for it is susceptible of embodiment in various forms all coming within the scope of the claims which follow.

What is claimed is:

1. In a machine of the class described, the combination of multiplicand entry receiving means; multiplier entry receiving means; multiplying means controlled by said multiplicand and multiplier entry receiving means; a shiftable product accumulator having denominational order elements actuated by said multiplying means; shifting means for shifting said product accumulator; a first operating means for operating said shifting means to shift the accumulator denominationally from a starting position as the multiplication progresses; product printing means having denominational type carriers set under control of said accumulator to print products; a second means for operating said shifting means to return the product accumulator a predetermined number of denominational orders toward starting position at the beginning of a product printing operation and the remaining denominational orders to starting position near the end of a product-printing operation to thereby align certain denominational order elements with the denominational type carriers for printing certain digits of the product and thereafter returning the accumulator to starting position and means selectively operable to couple said shifting means to said first operating means for operation thereby as multiplication progresses and to couple said shifting means to said second operating means for operation thereby during a product-printing operation.
2. In a machine of the class described, the combination of a multiplicand entry receiving means for a multiplicand composed of a whole number part and a decimal part; a multiplier entry receiving means for a multiplier composed of a whole number part and a decimal part; multiplying means controlled by said multiplicand and multiplier entry receiving means; a product accumulator having denominational order elements actuated by said multiplying means; reversibly operable means to shift said accumulator; means to drive said shifting means in one direction to shift said product accumulator from a starting position denominational as multiplying progresses; printing means controlled by said product accumulator and including denominational type carriers for printing whole numbers and decimal places less in number than the decimals in said product; and means to drive said shifting means in a reverse direction during the first part of a product-printing operation to return the accumulator partially to starting position to locate the accumulator so that the denominational elements representing the whole number part and decimal part of the product will control the corresponding denominational type carriers to print the whole number part and as many decimal places in the product as there are type carriers and to eliminate the recording of decimal places in excess of the number of decimal place type carriers and to drive the shifting means during the last part of the product-printing operation to return the accumulator to starting position.
3. In a partial product multiplying machine, the combination of a member having a predetermined number of teeth; a second member having a related predetermined number of teeth; means to selectively operate one of the members one or more times in either of two directions and the other one of the members once in either of two directions; means selectively settable according to the digits one to nine for controlling the number of operations and direction of operation of

the members by the operating means; and means set by the members, as they are operated, according to the units digits of the partial products of one digit times any of the digits from one to nine, depending upon the number of operations and direction of operation given to the members.

4. In a partial products type of multiplying machine, a units partial product value computing means comprising a pair of elements, each element having teeth located in different planes thereon, corresponding planes in which teeth are located on both elements being selectable according to multiplicand digits and the number of teeth on both elements in each plane being such that upon various operations of the elements according to the multiplier digits, the combined effective operation of the teeth will cause the required units partial product value to be computed; means shiftable according to multiplicand digits to select the corresponding planes on both elements; and selectively operable means to operate one of said elements one or more times in either of two directions and the other of said elements one time in either of said two directions according to said multiplier digits.

5. In a partial product multiplying machine, a pair of rotatable members each having a predetermined related number of teeth thereon, the number of teeth on each of the members being chosen so that said teeth, when taken alone one or more times, or additively or subtractively in combination, will form the units digit of the partial products of one digit times any of the digits one to nine; multiplier control means; variable drive means for driving one of said members one or more times in either of two directions and the other one of said members one time in either of said two directions; and means operated by the multiplier control means in accordance with the value of the multiplier digit for controlling the direction and number of rotations of the rotatable members by the variable drive means.

6. In a partial product multiplying machine, a pair of rotatable members each having a predetermined related number of teeth thereon, the number of teeth on each of the members being chosen so that when taken alone once or twice or additively or subtractively in combination they will form the units digits of the partial products of one digit times any of the digits one to nine; multiplier control means; variable drive means for driving one of said members one or two times in either of two directions and the other one of said members one time in either of said two directions; means operated by the multiplier control means in accordance with the value of any multiplier digit for controlling the direction and number of rotations of the rotatable members by the variable drive means; a settable member operated by the rotatable members and set in accordance with said units digit of the partial product; a product accumulator; and means for transferring the units digit of the partial product, which has been set on the settable member, to the product accumulator.

7. In a partial product multiplying machine, the combination of a group of members having various preselected numbers of teeth; a second group of members related to the first group of members and having various preselected numbers of teeth; multiplicand entry receiving means; multiplier entry receiving means; selector means set by the multiplicand entry receiving means to select a related member in each group of members in accordance with a digit of the multiplicand;

means controlled by the multiplier entry receiving means for selectively operating one of the groups of members one or more times in one or another direction and the other group of members once in either of said directions, said selective operation of either or both of said groups of members depending upon the value of the multiplier digit; and a settable member coacting with the selector means and operated through the selector means by the teeth on the selected members, the operation of the teeth on the selected related members setting the settable member according to the units digit of the partial product of the digit of the multiplicand times the digit of the multiplier.

8. In a partial product multiplying machine, the combination of a tens value partial product member having groups of teeth thereon, which teeth in each group are equal in number to the maximum tens value of various partial products based on different multiplicand digits; a pair of units value partial product forming members having groups of teeth thereon, the number of teeth in each group on one of the units partial product value members being so related to the number of teeth in each group on the other units partial product value member that when the units value partial product members are variously operated, the combined number of teeth will be equal to the units values of the various partial products; means for operating the units value partial product members; multiplicand entry receiving means; means controlled by the multiplicand entry receiving means for selecting corresponding groups of teeth on the several units and tens members to select units and tens partial product values related to the multiplicand digits; multiplier entry receiving means; means controlled by the multiplier entry receiving means for controlling the operation of the tens value partial product member to operate the selecting means for the tens partial product value according to the tens partial product value, and controlling the operation of the units value partial product members by their operating means to operate the selecting means for the units partial product values according to the units partial product value; a product accumulator; and means for transferring the tens and units values of partial products to the product accumulator.

9. In a partial product multiplying machine, the combination of a multi-denominational order multiplicand entry receiving means; a multi-denominational order multiplier entry receiving means; tens value partial product means for each denominational order of the multiplicand; a pair of units value partial product forming means for each denominational order of the multiplicand; operating means for said units value forming means; control means for controlling the operation of the units value forming means by the operating means in accordance with values of the multiplier digits; selector means settable by the multiplicand entry receiving means in accordance with the multiplicand digits into engagement with the tens value means; selector means settable by the multiplicand entry receiving means in accordance with the multiplicand digits into engagement with the units value forming means; a product accumulator; means operable successively under control of the multiplier entry receiving means in accordance with the multiplier digits to operate the tens value means and to set the control means; said tens value means, when operated, being effective through its related selec-

tor means to enter the tens values of the partial product into said product accumulator while the units values of the partial products are being formed; means settable in accordance with the units digits of the partial products by the units value forming means through their selector means when the forming means are operated; and means operable after the tens values have been entered into the product accumulator for transferring the units values from the settable means to the product accumulator to form therein the complete product.

10. In a machine of the class described, the combination of a series of denominational pairs of devices selectively operable to build up the units components of partial products; variable drive means for operating said devices; a series of denominational devices from which the tens components of partial products can be obtained; an element for each denominational pair of the units component devices; an element for each denominational device for the tens components; means to position the elements selectively into engagement with the devices in proportion to the value of each related denominational digit of the multiplicand to obtain the components therefrom; means to store each denominational digit of the multiplier; means to reset the storage means one after another; means controlled by the resetting means according to values derived from the multiplier storage means to operate the tens components devices successively various amounts which are directly in proportion to the value of the various multiplier digits and to successively control the operation of the pairs of devices by their variable drive means in a predetermined manner according to the value of the various multiplier digits to successively form the components of partial products; a product accumulator to receive the partial products; and means whereby the elements transfer the components of the partial products to the product accumulator to form a complete product therein.

11. In a machine of the class described, adapted to perform multiplication by the partial product method, and having means for entering a multiplicand and a multiplier, the combination of denominational devices for building up the units components of partial products; denominational devices from which are obtained the tens components of partial products; means selectively operable to drive said units component devices; means, comprising a cylinder positionable in proportion to each denominational digit of the multiplier in succession, for controlling the operation of the units component devices by their drive means to form units values of partial products; means to successively operate the tens value devices from a normal position different distances which are in direct proportion to each denominational digit of the multiplier; selective devices positionable into engagement with the units and tens component devices proportionate to the digits of the multiplicand to collect the partial products from the devices when the devices are operated; a product accumulator for receiving the partial products; and means controlled by the selecting devices to enter in the product accumulator the partial products which have been collected by the selecting devices, in order to obtain a complete product in said product accumulator.

12. In a machine of the class described, the combination of key-controlled means to enter a multiplicand; key-controlled means to enter a

multiplier; a plurality of elements having means thereon from which partial product components may be obtained; means controlled by the multiplier entering means to operate certain of the partial product elements in proportion to each multiplier digit to obtain one component of the partial products and other of the elements selectively different predetermined extents according to the multiplier digits in order to form another component of partial products which may be obtained therefrom; a plurality of members selectively engageable with the means on the partial product elements to obtain the partial product components therefrom; means controlled by the multiplicand entering means to move the members according to the digits of the multiplicand to select the partial product components accordingly; a product accumulator; and means operatively connecting the members to the accumulator to enable the selected partial product components obtained from the devices by the members to be accumulated, the operation of the elements according to each multiplier digit causing the partial products based on that digit to be formed, from which partial products those related to the multiplicand digits are selected and the selected partial products are transmitted to the product accumulator to obtain a complete product.

13. In a machine of the class described, adapted to perform multiplication by the partial product method, the combination of multiplicand entry receiving means; multiplier entry receiving means; a plurality of elements operable various predetermined extents for various multiplier digits and having thereon means to form sets of units components of partial products based on the multiplier digit which controls the operation of the elements; means to operate said elements; a plurality of elements having thereon means from which the tens components of partial products can be obtained when the elements are operated extents proportional to the multiplier digits; selective devices operable to engage with the means on the units component elements to obtain the units components therefrom; selective devices operable to engage with the means on the tens component elements to obtain the tens components therefrom; means controlled by the multiplicand entry receiving means to move the selective devices into engagement with the means on the elements in accordance with the digits of the multiplicand to select, from all the possible partial products, those corresponding to the multiplicand digits; means controlled by the multiplier entry receiving means to operate the tens component elements in proportion to each digit thereof to obtain tens components of partial products and to control the operating means for the units component forming elements to operate the elements various of said predetermined extents corresponding to the multiplier digits to form the units components; a product accumulator; and means to selectively transmit the selected partial products from the selective devices to the accumulator so that the selected partial products may be accumulated.

14. In a machine of the class described adapted to perform multiplication by the partial product method, the combination of multiplicand entry receiving means; multiplier entry receiving means; means for computing the units component values of partial products, said units components partial product computing means including a plurality of elements variably oper-

able according to each multiplier digit, means to operate the elements, a control member settable to various positions according to multiplier digit values to selectively control the various operations of the elements by their operating means, and means on the elements to produce units component values as the elements are operated; means for supplying the tens component values of partial products, said tens component supplying means including a plurality of elements movable different extents proportional to multiplier digits, and means on the elements to produce the necessary tens components when the elements are moved according to multiplier digit values; means controlled by the multiplier receiving devices to set the control member according to each multiplier digit to cause the variable operation of the units component devices to produce the units components based on that digit and to operate the tens component devices to produce the necessary tens component values; collector means selectively engageable with said elements to receive said partial product components; means controlled by the multiplicand entry receiving devices to move the collector means into engagement with the elements to select from the partial products formed with the multiplier digit as a base, those related to the multiplicand digits; a product accumulator; and means selectively operable to transmit partial product components from the collector means to the product accumulator so that the collected partial product components may be accumulated therein.

15. In a partial product multiplying machine, the combination of multiplicand entry receiving means; multiplier entry receiving means; elements operable extents proportional to the value of the multiplier digits and having means thereon to provide the tens components of product tables based on any multiplier digit when the elements have been operated in proportion to that digit; elements operable different predetermined extents according to different multiplier digits and having thereon means to build up the units components of product tables based on any multiplier digit when the elements are operated the predetermined extent corresponding to that multiplier digit; means to operate the units component elements; a control member differentially settable to control the operation of the units component elements by their operating means; means controlled by the multiplier receiving means to operate the tens component elements in proportion to the multiplier digits and to set the control member to cause the operating means for the units components elements to operate the elements predetermined extents as required by the multiplier digits; means engageable with the means on the units and tens component members to obtain the components therefrom; and means operated by the multiplicand entry receiving device to move the last-mentioned means into engagement selectively with the means on elements according to multiplicand digits to select, from the units and tens components formed according to any multiplier digit, those components corresponding to the multiplicand digits.

16. In a machine of the class described, the combination of means to enter multiplicand and multiplier data; multiplicand entry receiving devices; multiplier entry receiving devices; a pair of units components devices for each denominational order of the multiplicand, which devices are operated in a different predetermined manner for each multiplier digit and have means thereon

for building up units components of partial products based on different multiplier digits depending upon the manner in which the devices are operated; means for operating said units component devices; a tens component device for each denominational order of the multiplicand, which devices are operated different predetermined extents according to each multiplier digit and have means thereon to provide tens components of partial products based on different multiplier digits when the devices are operated said predetermined extents corresponding to said digits; selecting means selectively engageable with the means on the devices to select from the units and tens components based on any multiplier digit, those related to the multiplicand digits; means controlled by the multiplicand entry receiving device to cause the selective engagement of the selecting means and the devices according to the digits of the multiplicand; means controlled by the multiplier entry receiving devices according to multiplier digits to cause the operation of the tens devices predetermined extents and to control the manner in which the units devices are operated by their operating means; a product accumulator; and means selectively transmitting the selected partial product components from the selecting means to the product accumulator to form the complete product therein.

17. In a machine of the class described arranged to perform multiplication by the partial product system, the combination of a series of devices having thereon means from which components of partial products can be obtained, certain of the devices being operable different extents proportional to multiplier digits to produce all the values necessary to provide one component of partial products and the remaining devices being operable selectively one or more times and in either of two directions according to various multiplier digits to produce all the values necessary to form the other component of partial products; means to operate said remaining devices one or more times and in either of two directions; multiplier entry receiving means; means successively controlled by the multiplier entry receiving means, according to the digits of the multiplier, for operating the certain devices different extents proportional to the multiplier digits and for controlling the number and direction of the operation of the remaining devices by their operating means according to the multiplier digits to cause components based on that digit to be formed by said devices; multiplicand entry receiving means, selecting means moved into engagement with the means on said devices under control of said multiplicand entry receiving device to select and obtain from the devices the partial product components according to multiplicand digits; a product accumulator; and means selectively transmitting partial product components from the selecting means to the product accumulator to enable the partial product components obtained from the devices to be transferred to the accumulator to be accumulated therein.

18. In a partial product type of multiplying machine, the combination of means for entering a multiplier and a multiplicand; multiplicand entry receiving means; means to store each digit of the multiplier; a pair of units component devices for each denominational order of the multiplicand, which devices are operated in a different predetermined manner for each multiplier digit and have means thereon for building up the units components of partial products based on any

multiplier digit when they are operated in the manner related to that multiplier digit; means for operating said units component devices; a tens component device for each denominational order of the multiplicand, which devices are operated different predetermined extents according to each multiplier digit and have means thereon to provide tens components of partial products based on different multiplier digits when the devices are operated said predetermined extents corresponding to said digits; selecting devices for each denominational order and selectively engageable with the means on the units and tens devices to be actuated thereby according to units and tens components of partial products when the devices are operated according to any multiplier digit; means to position the selecting devices into engagement with the means on the units and tens value devices according to the denominational digits of the multiplicand to select, from the partial products based on any multiplier digit, those partial products which are related to the multiplicand digits; means to progressively clear each denominational digit from the multiplier storage means; means controlled by the clearing means successively according to each digit of the multiplier, as the storage means are cleared progressively, for operating the devices from which the tens values are obtained, different predetermined extents according to the values of the multiplier digits and for successively controlling the operation of the units component devices by their operating means various predetermined manners depending upon the values of the multiplier digits to thereby form partial products according to said digits; means to accumulate partial products to obtain a complete product; means selectively transmitting the partial products received by the selecting devices from said devices to the accumulating means; and means to denominational shift the accumulating means after the partial product for each multiplier digit has been transferred thereto.

19. In a machine of the class described, adapted to perform multiplication by the partial product system, the combination of key-controlled means for entering a multiplicand; key-controlled means for entering a multiplier; denominational devices variably operable according to different multiplier digits and having means thereon to produce the units values of partial products based on any multiplier digit when the devices are operated according to that digit; denominational devices from which the tens values of partial products can be obtained when the devices are operated different extents according to multiplier digits; operating means for the units value producing devices; a control cylinder having control means thereon; means positionable according to each digit of the multiplier in succession to operate the tens value devices to obtain the tens values of the partial products and to position said cylinder differentially according to the multiplier digits; means to impart lateral shifting movement to the cylinder after each positioning to enable the control means thereon to control the operation of the units value devices by their operating means to form the units values of the partial products; selecting devices engageable with the units and tens value devices, said selecting devices being positionable by the multiplicand entering means into selective engagement with the units and tens value devices corresponding to

the denominational digits of the multiplicand, and said selecting devices being set according to the proper components of the partial products by the means on the units and tens value devices as said partial products are formed; a product accumulator; and means selectively transmitting the setting of the selecting devices to the product accumulator to transfer the partial products represented by the setting of the devices to the product accumulator.

20. In a machine of the class described, adapted to perform multiplication by the partial product system, the combination of key-controlled means to enter a multiplicand; key-controlled means to enter a multiplier; denominational devices from which the units values of the partial products can be obtained, said devices being operable in a different manner for each multiplier digit and having elements in each 15 denomination for forming the units values of partial products when the devices are operated; denominational devices for providing the tens values of the partial products, said devices being operable different extents according to multiplier digits and having elements in each denomination from which the tens values of the partial products can be obtained; product accumulator for accumulating the partial products to obtain a complete product; means to 20 operate the units values partial product devices; denominational elements to store each denominational digit of the multiplier; means including a cylinder having control members thereon to govern the manner in which the operating means for the units value operates these devices; means to successively reset the multiplier storing elements and position the cylinder in proportion to the various multiplier digits to control the 25 operation of the units value partial product devices by their operating means in accordance with the digits of the multiplier and also cause the operation of the tens values devices different extents according to the digits of the multiplier; denominational selecting devices adapted to be 30 positioned by the multiplicand entering means in selective engagement with the elements of the units and tens partial product devices according to the digits of said multiplicand to select units and tens values of partial products 35 according to the digits of the multiplicand, said selecting devices actuated by the elements differentially according to the units and tens values of the partial products; storage means set by the units component selecting means; means to transmit the selected units and tens partial 40 product values from the storage means and the tens component devices respectively to the product accumulator to obtain a complete product; and means to shift the product accumulator denominational after the units and tens values 45 of partial products based on each multiplier digit have been obtained and entered into the product accumulator.

21. In a machine of the class described, the 50 combination of key-controlled means to enter multiplicand data and multiplier data; multiplicand entry receiving devices; multiplier entry receiving devices; devices for each denominational order of the multiplicand and operable in a different manner for each multiplier digit to 55 build up the various units components of partial products based on that digit; means for variably operating the units component devices; devices for each denominational order of the multiplicand and operable different extents propor- 60

tional to each multiplier digit to provide the tens components based on that digit; means controlled by the multiplier entering means to drive the tens component devices in proportion to the denominational digits of the multiplier and to control the different operations of the units component devices by their operating means according to the digits of the multiplier; a product accumulator for accumulating the partial products; and transferring means adapted to be positioned by the multiplicand entering means into selective engagement with the units and tens component devices according to the denominational digits of the multiplicand to select from the components formed according to any multiplier digit, those related to the digits of the multiplicand, said transferring means adapted to transfer the selected partial product components to the product accumulator to obtain a complete product.

22. In a machine of the class described, adapted to perform multiplication by the partial product system, the combination of key-controlled means to enter a multiplicand; key-controlled means to enter a multiplier; a plurality of denominational elements operable in a different manner for each multiplier digit for forming the units and tens components of all possible partial products based on that multiplier digit; a product accumulator; selecting devices selectively engageable with the elements to select from the partial products components formed for any multiplier digit those related to the multiplicand digits; means controlled by the multiplicand entering means to position the selecting devices to selectively engage the units and tens component elements, in accordance with the digits of the multiplicand; means controlled by the multiplier entering means to store each digit of the multiplier; means to clear the storing means order by order, beginning with the lowest order; means rendered effective by the clearing means and under control of the multiplier storage means successively to drive the elements in accordance with the digits of the multiplier order by order, whereupon the partial products are obtained by the selecting devices; and means to selectively transmit partial product components from the selecting devices to the product accumulator to transmit thereto the selected partial product components to obtain a complete product.

23. In a machine of the class described, adapted to perform multiplication by the partial product system, the combination of key-controlled means to enter a multiplier; key-controlled means to enter a multiplicand; a plurality of denominational elements variably operable according to each possible multiplier digit and having means thereon which are operable to build up all the units components of partial products according to any particular multiplier digit when the elements are operated according to that digit; a plurality of denominational elements operable extents proportional to the value of each possible multiplier digit and having means thereon to provide the necessary tens components of partial products based on any multiplier digit when the elements have been operated in proportion to that digit; a product accumulator for accumulating the partial products to form a complete product; selecting devices selectively engageable with the means on the units component elements and displaced thereby according to the units components of the partial products; storage

means displaced by the units component selecting devices according to the selected units components; selecting devices selectively engageable with the means on the tens component devices and displaced thereby according to the tens components of the partial products; means controlled by the multiplicand entering means to position the units and tens component selecting devices selectively in engagement with the means on the units and tens component elements, according to the digits of the multiplicand to select the components of partial products according to the multiplicand digits; means controlled by the multiplier entering means to store each digit of the multiplier; means to clear the multiplier storing means order by order, beginning with the lowest order; a control cylinder positioned different extents by the multiplier clearing means in proportion to each digit of the multiplier; means connecting the cylinder to the tens component devices so that said devices will be actuated in proportion to the multiplier digits and displace related selecting devices according to the tens components of the partial products; variable actuating means for the units component forming devices; projections on the cylinder selectively located thereon according to each digit of the multiplier to control the variable actuating means, said projections being positioned in relation to said variable actuating means upon positioning of said cylinder different extents; means to impart lateral shifting movement to the cylinder after it is positioned in proportion to the multiplier digit; means operated by the projections to render the variable actuating means effective to actuate the units component forming devices in accordance with the digits of the multiplier so that the means on the units component devices can displace their related selecting devices according to the units components of the partial products; and means selectively operable to connect the units component storage means and the tens component selecting devices to the product accumulator so that the displacement of the selecting devices may be transferred to the accumulator to enable the complete product to be formed therein.

24. In a machine of the class described adapted to perform multiplication by the partial product system, and having key-controlled means for entering a multiplicand and a multiplier, the combination of means to compute units component values of partial products, said means including a pair of elements for each denominational order of the multiplicand, means to operate the elements selectively one or more times and in either of two directions according to multiplier digits, a control member differentially settable according to multiplier digits and having means thereon to control whether one or both elements of each pair will be operated by their operating means and also to control the number and direction of their operations, and means on the elements for building up the various units component values based on different multiplier digits when the elements are operated according to that digit; means for supplying the tens component values of partial products, said means including an element in each denominational order of the multiplicand and operable different extents proportional to the multiplier digits, and means on the elements to produce the necessary tens components values based on any multiplier digit when the elements are operated according to that digit; means settable by the multiplier

entry means to store the digits of the multiplier; means controlled by the multiplier storage means to differentially position the control member successively according to the multiplier digits to control the operation of the units component elements by their operating means and to operate the tens component elements in proportion to said digits to produce the tens components of partial products related to said multiplier digits; selecting means to selectively engage the means on the units component elements to be displaced thereby according to the values of the units components when the elements are operated; storage means displaced by the units component selecting means according to the value of the units components; selecting means to selectively engage the means on the tens component elements to be displaced thereby according to the values of tens components when the elements are operated; means controlled by the multiplicand entering means to position the units and tens component selecting means opposite the means on their related elements so that the selecting means will select and be displaced according to the components related to the multiplicand digits; a product accumulator in which the components are accumulated; and means selectively connecting the storage means and the tens selecting means to transmit the displacement of the selecting means to the product accumulator to form the complete product.

25. In a machine of the class described, adapted to perform multiplication by the partial product system, and having key-controlled means to enter a multiplicand and a multiplier, the combination of means to compute units components of partial products, said computing means including two sets of wheels for each denominational order of the multiplicand, each set of wheels containing wheels corresponding to multiplicand digits 1 to 9 and having thereon predetermined numbers of teeth for forming units components of partial products when the wheels are differently operated according to multiplier digits, means for differently operating said sets of wheels selectively one or more times and in either of two directions, and control means controlled in accordance with multiplier digits to control whether either or both sets of wheels will operate and also to control the number and direction of their operations; means for providing tens components of partial products, said providing means comprising a set of wheels for each denominational order of the multiplicand, each set of wheels containing wheels corresponding to the multiplicand digits 2 to 9 and having thereon teeth so located that when the sets of wheels are operated different extents proportional to multiplier digits the tens components of partial products based on those multiplier digits can be obtained; means 60 displaceable by the teeth on the sets of wheels when they are operated; means controlled by the multiplicand entering means to move the displaceable means opposite those wheels corresponding to the various multiplicand digits to obtain from the computing means and the providing means the proper partial product component values; storage means set by the units component displaceable means; means controlled by the multiplier entering means to store each digit of the multiplier; means to clear the multiplier storing means order by order, beginning with the lowest order; means whereby the clearing means operates the sets of tens component providing wheels different extents proportional 65

to each multiplier digit in succession and sets the control means to control the operation of the sets of wheels of the computing means by their operating means according to each digit of the multiplier; a product accumulator; means to selectively connect the storage means or the tens component displaceable means to the product accumulator to transfer partial product component values represented by their displacement to the product accumulator to obtain a complete product therein; and means to shift the product accumulator denominational as multiplication progresses.

26. In a multiplying attachment for an accounting machine, said multiplying attachment adapted to multiply factors containing whole numbers and decimals, and said accounting machine comprising keys for the entering of multiplicands and multipliers in the multiplying attachment, the combination of a tens partial product component device for each denominational order of the multiplicand, said devices having wheels with teeth so located thereon that the tens components of the partial products can be obtained when the wheels are moved proportional to the multiplier digits; two units partial product component devices for each denominational order of the multiplicand, said devices being variably operable differently for each multiplier digit and having wheels with teeth for building up the units component values of the partial products based on any multiplier digit upon the operation of the devices according to said digit; means for variably operating the units partial product component devices; a product accumulator for accumulating the partial products to form a complete product; selecting means selectively engageable with the teeth on the wheels of the units partial product devices and actuated thereby according to the units components of partial products; intermediate devices actuated by the units component selecting means; selecting means selectively engageable with the teeth on the tens partial product component devices and actuated thereby according to the tens components of partial products; means to store each denominational digit of the multiplier; connections between the accounting machine and the units and tens selecting means and the multiplier storing means, whereby the entering of the multiplicand positions the units and tens selecting means according to the denominational digits of said multiplicand to select the partial product components related to the multiplicand digits, and the entering of the multiplier positions the multiplier storing means according to the digits of the multiplier; means to clear the multiplier storing means order by order; means controlled by the clearing means to operate the wheels of the tens component devices proportional to each digit of the multiplier in succession to form tens components of partial products corresponding to each digit, and to control the variable operation of the wheels of the units component devices by their operating means to build up units components of partial products related to each digit; means to selectively connect the intermediate devices and the tens component selecting devices to the product accumulator to transmit the components to the product accumulator; and means to advance the product accumulator denominational as multiplying progresses.

27. In a machine of the class described, the combination of multiplicand entry receiving means; multiplier entry receiving means; multi-

plying means comprising tens component of partial product forming means and means containing predetermined sub-values from which the various units components of partial products can be built up; means settable under control of the multiplicand entry receiving means for receiving the tens components of partial products from the tens component forming means; means for enabling the units components of partial products to be built up from the sub-values and including means settable under control of the multiplicand entry receiving means; means for operating the means containing sub-values; control means for said operating means; means operated under control of said multiplier entry receiving means to operate the tens component forming means and to set the control means to cause the operating means to drive the sub-value means to cause the units components to be built up; a product accumulator; means to transfer the tens components of partial products to the product accumulator when the tens component forming means is operated and while the means containing sub-values is being operated to cause the units components of partial products to be built up; and means to transfer the units components of partial products to the product accumulator after the units components have been built up and after the tens components of partial products have been entered into said product accumulator.

28. In a machine of the class described, the combination of settable means; a first member having means thereon corresponding to a predetermined sub-value for causing the setting of the settable means; a second member having means thereon corresponding to a predetermined sub-value related to the sub-value on the first member for causing the setting of the settable means; and means to cause the selective operation of the members in accordance with multiplier digits; the value of the setting of said settable means as derived from the sub-value means on the members upon the operation of the members, either singly or in combination, corresponding to the units components of partial products of a digit times any of the digits from one to nine.

29. In a partial product multiplying machine, the combination of a tens component of partial product member having means thereon from which may be obtained the tens components of partial products when it is operated predetermined extents according to digits of one factor;

means cooperating with the tens components partial product member to receive the tens components therefrom; a pair of units component of partial product members, each of said units value members having means thereon corresponding to predetermined values from which all the units components of partial products can be built up by the selective operation of either or both of said members selectively in a predetermined manner according to the digits of said one factor; means cooperating with the units component partial product members to enable the units partial product components to be built up from the predetermined values when the units component of partial product members are operated; means for operating the units component of partial product members; and means for operating the tens component member and controlling the selective operation of the units component members by their operating mechanism according to the digits of one factor in a multiplying operation.

30. In a machine of the class described, adapted to perform multiplication by the partial product system, the combination of a plurality of devices containing predetermined sub-values from which the units components of the partial products can be built up; a plurality of devices from which the tens components of the partial products can be obtained; selective devices engageable with the devices related to the units components of partial products to enable the values of the units components to be built up from the sub-values when the devices are operated; selective devices engageable with the devices related to the tens components of partial products; means to position the selective devices in engagement with the units and tens component devices according to the digits of the multiplicand; means to operate the devices from which the tens partial product components are derived, in proportion to each digit of the multiplier to obtain tens components of partial products; means to operate the units component devices selectively one or more times according to each multiplier digit to cause the units component of each partial product to be formed from the sub-values; a product accumulator adapted to receive the tens and units components of the partial products; and means whereby the selective devices transmit the tens and units components of the partial products to the product accumulator to obtain a complete product.

HANS UHLMANN.

CERTIFICATE OF CORRECTION.

Patent No. 2,335,368.

November 30, 1943.

HANS UHLMANN.

It is hereby certified that error appears in the printed specification of the above numbered patent requiring correction as follows: Page 3, second column, line 9, for "cycles" read --operations--; page 11, first column, line 46, for "stud 362" read --stud 352--; page 15, second column, line 29, for "The" read --Two--; page 17, second column, line 60, for "at" read --set--; page 23, second column, line 55, claim 17, strike out the comma and insert instead a semi-colon; and that the said Letters Patent should be read with this correction therein that the same may conform to the record of the case in the Patent Office.

Signed and sealed this 1st day of February, A. D. 1944.

Henry Van Arsdale,

(Seal) Acting Commissioner of Patents.
